DISPATCHING AND SCHEDULING SYSTEM

David Carl Larson, Yonkers, N. Y., assignor to
 Otis Elevator Company, New York, N. Y., a corporation of New Jersey

Application July 31, 1930, Serial No. 471,926

46 Claims. (Cl. 177—336)

The invention relates to dispatching and scheduling systems, and particularly to such systems as applied to a plurality of elevators arranged in a group.

5 In the operation of a plurality of elevators arranged in a group, it is important that some supervisory control be exercised over them so that efficient and satisfactory service may be derived therefrom. Supervisory control may be 10 effected manually by an experienced starter who directs his sole attention to the task. The attention of such a starter, however, is frequently diverted by prospective passengers asking questions and by other causes, all to the impairment 15 of the elevator service. Furthermore, such complete manual supervisory control is always dependent upon the human element, and thus subject to its fatigue, bad judgment, and irregularities. The object of this invention is to exercise 20 supervisory control over a group of elevators through the medium of mechanical and electrical equipment that eliminates the undesirable features of complete manual supervisory control, and that, in addition, incorporates sufficient 25 flexibility to adapt the supervisory functions to the variety of operating conditions that may arise in order to obtain efficient and satisfactory elevator service. Illustrative of the variety of 30 general operating conditions with which such an equipment must cope, may be mentioned the heavy inward flow of traffic in the morning, the heavy outward flow of traffic in the evening, the peak two-way flow of traffic during the middle of the day, and the normal two-way flow of 35 traffic during other periods of the business day. In addition, the equipment must cope with numerous other operating conditions some of which are more or less of a transient and varying nature. Such other operating conditions may be due, for 40 example, to temporary deviations from the traffic conditions that are average for the time of day under consideration. As a result of these transient and varying operating conditions, one car may consume, during one trip, more than the 45 average time, while a succeeding car may consume, during a similar trip, less than the average time.

The main feature of this invention is the provision of a supervisory control employing automatically operating mechanical and electrical equipment that is capable of effectually coping with the variety of both the general and transient operating conditions that may arise in a bank of elevator cars during the course of a 55 day.

Other features and advantages will become apparent from the following description and appended claims.

In carrying out the invention, there is provided means for ordering the operator of each car, when that car is at a terminal floor, to start that car away therefrom. The preferred arrangements, which are those herein described, employ two visual signals within each car, one signal for ordering the starting of the car from the lower terminal floor, and the other signal for ordering the starting of the car from the upper terminal floor. There is also provided apparatus for controlling the operation of these start or dispatch signals so that, under certain operating conditions, cars are dispatched normally at regular intervals of time from each of the lower and upper terminal floors. For flexibility, it is provided that these time intervals may be shortened or lengthened. Provision is made so that if there is no car at a terminal floor eligible to be dispatched at the time that a car normally is dispatched therefrom, the start signal initiated by the apparatus at that instant is maintained effective so that it is given to the car first to arrive at the terminal floor and become eligible to be dispatched. In the event that there has been an excessive delay somewhere so that no car has departed from a terminal floor by the time a given percentage of a time interval has elapsed, it is provided that all timing operations are suspended until a car does leave the terminal floor. As a result of these operations, when they are made effective at both the lower and the upper terminal floors, the supervisory control tends to maintain an even number of cars so that at any instant one-half the cars are operating on an up trip, while the other half are operating on a down trip. This relationship among the cars may, for convenience, be considered as a "balanced" one. The maintenance of such a "balanced" relationship among the cars, it may be seen, provides for equality of service in both directions. As provision is made to render any number of cars less than the total number in the group subject to the supervisory control, it may, under certain conditions, be desirable to render an odd number of cars subject to the supervisory control. In such event it is provided that a relationship among such an odd number of cars that is analogous to the "balanced" relationship among the even number of cars may be maintained. This is effected upon the operation of a certain switch so that dispatch signals for cars at the upper terminal floor are initiated half an 110

interval after the time when they are normally initiated for an even number of cars. As a result of this displacement in the time at which cars are dispatched from the upper terminal floor, 5 the odd car is, in normal situations, dispatched from the upper terminal floor during the interval between the dispatch of successive cars at the lower terminal floor.

It is further provided that the giving of the 10 dispatch signals at the lower and upper terminal floors may be so interrelated that the scheduled time for a car on an up trip may be made less than, equal to, or greater than the scheduled time for a car on a down trip. As a 15 result of this provision, the round trip time may be apportioned in varying percentages between the up and down trips in order to accommodate traffic conditions in any particular building or time of day.

20 Another provision of the invention is that at each terminal floor the dispatch signal installed by the supervisory control system for that terminal floor is given to one car only of those that may be at that terminal floor at that time. This 25 is effected by providing a system of relays such that when the relay for one car operates, after the arrival of that car at the terminal floor, to render that car eligible to receive a dispatch signal, the relays for all the other cars are rendered 30 inoperative. As a result no other car then at the terminal floor, nor no other car subsequently arriving thereat, is eligible to receive the dispatch signal given to that one car. In addition, provision is made so that one car continues to 35 receive the starting signal until that car has actually departed from the terminal floor. This is effected by providing that the resetting of devices that control the operation of the start signals is accomplished only upon the travel of the 40 car away from the terminal floor. The operator of a car is thus continuously informed, after the dispatch signal is once given to that car, that his car is being ordered to leave the terminal floor, and he cannot cancel the order except upon 45 compliance therewith.

There is also provided, in carrying out the invention, means for informing a starter or other supervisory official of the performance of the cars in the group, and of the responsiveness of 50 the car operators. The arrangements illustrated employ two starter's lights, one for indicating conditions at the lower terminal floor, and the other for indicating conditions at the upper terminal floor. The arrangements are such that 55 when a dispatch signal is initiated for ordering a car to leave a terminal floor, but at that time no car is at that terminal floor capable of receiving such dispatch signal, the starter's light for that terminal floor is caused to illuminate with a steady light. When a car arrives and receives the dispatch signal, the starter's light is caused to illuminate with a flickering light. This flickering of the starter's light is caused to continue until the car departs from the terminal floor. 60 As a result, the steady light is a signal that a dispatch signal is being given, but no car is at hand to receive it; the change from a steady to a flickering light is a signal that a car has arrived and is receiving the dispatch signal; and 65 the continued flickering of the starter's light is a signal that the car has not left in response to the order to start. By reference to indicators such as are extant that indicate the positions of the cars, the starter may normally determine 70 which of the cars is receiving the dispatch signal.

Another provision of the invention is that, in the event that it is desired to reduce to a minimum the period during which a car may be at a terminal floor waiting for the expiration of a scheduling interval after the giving of a dispatch signal to the preceding car until this, the succeeding car, may receive a dispatch signal, the dispatch signal may be given to a car immediately upon its arrival at a terminal floor and its becoming eligible to receive such signal. Such an immediate giving of the dispatch signal may be desirable when the traffic in one direction predominates over that in the other, or when the traffic is otherwise heavy. This may occur, for example, in the morning, when the traffic is predominately up, with the result that it may be desirable to eliminate the dead waiting time at the upper terminal floor so that the cars may return to the lower terminal floor as quickly as possible. In the evening an analogous situation may arise with respect to the lower terminal floor, for then the traffic may be predominately down, with the result that it may be desirable to eliminate dead waiting time at the lower terminal floor so that the cars may return to the upper terminal floor as quickly as possible. Such an immediate giving of the dispatch signal for a terminal floor may be effected by the operation of a switch for that terminal floor so that a by-pass circuit is established across a pair of contacts 100 the engagement of which normally controls the initiation of the dispatch signal for that terminal floor. The engagement of these contacts is thus simulated, so that as a result, as soon as a car arrives at that terminal floor and becomes 105 eligible to receive a dispatch signal, a dispatch signal is given to that car.

The invention also provides that, when so desired, the cars may be "run wild". Such an operation of the cars may be desired when traffic 110 is abnormally heavy, and it is desired to push the cars to the limit of their capacity. In such event the scheduling interval may be dispensed with at both the lower and the upper terminal floors, and dispatch signals given to each car 120 at each terminal floor as soon as the car arrives at terminal floor and becomes eligible to receive such signals. In the arrangements illustrated such an immediate giving of the dispatch signal at both terminal floors may be effected by simultaneously operating the switch described in the preceding paragraph both for the lower and the upper terminal floor.

Under certain conditions it may be desirable to prevent the departure of a car from a terminal 130 floor until the receipt by that car of a dispatch signal, or order to start. In such event it is provided in one of the arrangements illustrated that, as soon as a car arrives at a terminal floor, the starting control circuit for that car may 135 be rendered ineffective for causing the starting thereof. It is further provided that upon the receipt by that car of a dispatch signal, the starting control circuit may be restored to an operative condition. Accordingly with such provisions, an operator of a car is unable to disobey instructions to leave only upon receiving an order to start.

An additional provision of the invention is that only one hall light at a terminal floor may 145 be illuminated at a time, that one hall light being for the one car at the terminal that is eligible to receive a dispatch signal or that is already receiving a dispatch signal. Hence the hall light for the car that is the first to leave the terminal 150

floor is illuminated to direct prospective passengers to that car. In one of the arrangements illustrated, this operation is effected by placing in the terminal floor hall light circuit for a car 5 a pair of forward contacts of the relay which, upon operation, renders that car eligible to receive a dispatch signal at that terminal floor. As a result, the terminal floor hall light for that car is illuminated when that car becomes eligible 10 to receive a dispatch signal. If desired a notification light, visible to the operator within a car, may be provided to notify the operator that his car is the next to be dispatched, and that prospective passengers are being directed to his 15 car. In one of the arrangements illustrated such notification lights, one for each terminal floor, are connected in parallel with the hall light for the corresponding terminal floor. As a result each notification light is illuminated at the 20 same time as the corresponding terminal floor hall light.

In the drawings:—

Figure 1 is a schematic diagram of a four car elevator bank illustrating one relative position 25 of the cars thereof.

Figure 2 is a wiring diagram of a dispatching and scheduling system.

Figure 3 is an elevation of the timing motor and associated mechanisms for said system.

30 Figure 4 is a view along the line 4—4 of Figure 3.

Figure 5 is a detail showing the construction of a roller brush mounted on the crosshead of a floor selector and also showing a floor selector contact adapted to cooperate with the roller brush.

Figure 6 is a schematic diagram illustrating relative positions of cars in a three car elevator bank.

40 Figures 7 and 8, taken together, constitute a wiring diagram of a second dispatching and scheduling system.

Figure 9 is a detail showing a modified form 45 of floor selector contact which is preferably employed in the system of Figures 7 and 8, and

Figure 10 is a detail diagrammatically illustrating a switch utilized in the system shown in Figures 7 and 8.

Referring to Figure 1, there is shown a bank of 50 four elevator cars, cars Nos. 1, 2, 3, and 4, operating between two dispatch floors 11 and 12. These dispatch floors are normally, though not necessarily, the first floor and the top floor. The figure illustrates the position and direction 55 of travel of four cars at one instant in the cycle of events as a convenient starting point for the descriptions of the dispatching and scheduling systems that follow. There is provided in each car a suitable control panel on which are mounted the various control switches and signals for that car. For simplicity, Figure 1 illustrates the control panel for each car as mounting only operator's control switches 1—13, 2—13, 3—13 and 4—13 for cars Nos. 1, 2, 3, and 4 respectively; up 60 start lights 1—14, 2—14, 3—14 and 4—14 for cars Nos. 1, 2, 3 and 4 respectively; and down start lights 1—15, 2—15, 3—15 and 4—15 for cars Nos. 1, 2, 3 and 4 respectively. Suitably positioned so as to be convenient of access for the starter or other official is a dispatch panel 16 upon which are mounted various hand operated switches and certain other apparatus (not shown) to control the operation of the dispatching and scheduling system. These may include 65

the knife switches 125, 126, 127, 130, 1—51, 2—51, 3—51, 4—51, and the speed control switch 142, which are referred to later in more detail. Also mounted upon the dispatch panel, or elsewhere so as to be readily visible to the starter or other official, are two starters' lights; one designated 17, for the lower terminal floor, and the other, designated 18, for the upper terminal floor.

Figure 2 shows an arrangement of circuit connections for dispatching and scheduling the four car bank of Figure 1. In this Figure 2 no attempt is made to show the coils and contacts of the various electromagnetic switches in their associated positions, a "straight" diagram being em- 80

ployed wherein the coils and contacts of the various switches are separated in such a manner as to render the circuits involved relatively simple. In this diagram, the electromagnetic switches have been given letters in addition to the usual reference numerals, so that although the parts 85

of the switches have been separated for simplicity in showing the circuits, they may still be identified by means of the common letters. To further aid in simplifying the diagram, switches, 90

coils, contacts and other apparatus that corre- 95

spond for each car are similarly designated, with the exception of prefixes 1—, 2—, 3— and 4— to designate the car with which the part is em- 100

ployed. Thus 1—13 is the operator's control switch for car No. 1; 4—15 is the "down" start 105

light for car No. 4; 3—44 is the floor selector brush for car No. 3; coil U75 is the actuating coil of the up schedule relay U; contacts U63 are a pair of contacts of the up schedule relay; coil 1—LU64 is the actuating coil of the selective up 110

relay for car No. 1, contacts 1—LU67 are a pair of contacts of that relay; coil 2—LU64 is the actuating coil of the selective up light relay for car No. 2; and contacts 2—LU67 are a similar pair of contacts of the corresponding relay for car No. 2. 115

The electromagnetic switches are shown in their deenergized positions, hence the contacts thereof that are shown as separated are forward contacts and the contacts that are shown as engaged are back contacts. To further aid the reading of the 120

diagram, all stationary contacts are illustrated in cross section. The designations of the electro- 125

magnetic switches are as follows:—

K	Timing motor relay	125
U	Up schedule relay	
D	Down schedule relay	
UU	Up dispatching relay	
DD	Down dispatching relay	
LU	Selective up light relay	
LD	Selective down light relay	130
FU	Up flicker relay	
FD	Down flicker relay	

In the wiring diagram of Figure 2 there is 135 diagrammatically illustrated a timing motor 20 connected to suitable reduction gearing 21 to drive a shaft 22. Figure 3 shows constructional details of this apparatus. The motor 20, suitably mounted upon a vertical support 23, is arranged above the housing containing the gearing 21. 140 If desired, the gearing may include a set of spur gears 24 mounted outside of the housing so that a large range of rotational speeds for the shaft 22 may be readily obtained by the interchange of these spur gears 24 without disturbing the oil- 145 immersed gearing in the housing. The shaft 22 is provided with contact bridges 25, 26 and 27. The bridges are clamped between the jaws of arms 30, 31 and 32, respectively, from which they are insulated as by means of non-conducting 150

tubes 28. Each arm is adjustably mounted on the shaft 22, as by set screws 33, so that the angular spacing between the arms, and thus the contact bridges, may be set to any desired amount. 5 Figure 4 illustrates one satisfactory angular spacing.

The contact bridges are caused to rotate by the motor 20 in the direction indicated by the arrows in Figures 2 and 4. During the course of this 10 motion starting from the position in which the contact bridges have been shown, contact bridge 25 engages with a set of stationary contacts 34 and 35; contact bridge 26 engages with a set of stationary contacts 36 and 37, and after one-half 15 of a revolution of the shaft 22, with a set of stationary contacts 38 and 39; and contact bridge 27 engages with a set of stationary contacts 42 and 43, and after one-half of a revolution of the shaft 22, with a set of stationary contacts 40 and 20 41. Each set of stationary contacts comprises two metallic fingers of appropriate design suitably mounted upon the support 23. As may be seen, the engagement of each contact bridge with its stationary set of contacts results in the establishment of a circuit between the stationary contacts, and since the contact bridge is normally rotated at a definite speed, as is hereinafter described, the circuit between the stationary contacts is normally established at regular time intervals. 25

The wiring diagram of Figure 2 also diagrammatically illustrates selector brushes 1—44, 2—44, 3—44 and 4—44 which travel in accordance with the motions of the cars Nos. 1, 2, 3 and 4 respectively. This correlation of each selector brush with its corresponding car may be effected through the medium of a "floor selector" of suitable arrangement in which the selector brush may be mounted upon a travelling crosshead that 30 moves in accordance with the motion of the car for which it is provided. When each car is at the lower terminal floor the selector brush for that car engages with a terminal floor selector contact 45, individual to that car, and when each 35 car is at the upper terminal floor the selector brush for that car engages with a terminal floor selector contact 46 individual to that car. These terminal floor selector contacts may be stationarily mounted upon the floor selector at the positions corresponding to the terminals for which 40 they are provided. The selector contacts 45 and 46 are identical except that the upper terminal floor selector contacts 46 are invertedly mounted with respect to the lower terminal floor selector 45 contact 45. Figure 5 shows in more detail a selector brush while in engagement with a lower terminal floor selector contact. To a travelling member 100 there is fastened, as by bolt 99, a U-shaped metallic bracket 101 having arms 102 and 45 103, the former designated arm being shown as partly broken away. To the ends of these arms there is secured a metallic pin 104. This pin pivotally supports a metallic U-shaped member 105 having a conducting roller 106 rotatably mounted 50 thereupon by a pin 195. A removable locking strip 107 is provided to prevent the dislodgment of the member 105 from the pin 104. The member 105 is also provided with an extending strip 108 that extends through a hole in one end of 55 a metallic plate 110. To the other end of plate 110 is rotatably mounted a second conducting roller 111, as by means of pins 196. A compressed spring 112 is positioned between the arms 102 and 103 and arranged so that one of its ends engages 60 70 75 the plate 110, and the other of its ends engages

the travelling member 100 through the intermediary of an insert member 113. As a result of this construction the spring maintains the conducting roller 111 bearing against the conducting roller 106 and thus tends to rotate the member 105 which mounts the conducting roller 106 counterclockwise until the extending strip 108 engages with the insert member 113 as a stop. When the roller 106 is in engagement with a selector contact, as is shown in Figure 5, the member 105 is rotated clockwise to compress the spring 112 still further, and thus to insure, as a result of the bearing of roller 111 against roller 106, an excellent electrical circuit between the selector contact and the bolt 99. 80

The terminal floor selector contact 45 is supported upon a stationary bar 114 made of suitable insulating material. A metallic member 115 fastened to the insulating bar 114 by the bolt 117 is provided with a lip 116 that is bent over the edge of the bar. This lip is the surface adapted to be engaged by the roller brushes. A pair of lugs 118, provided on the member 115, pivotally support a metallic lever arm 47. A compressed spring 120 is positioned between the member 115 and the lever arm to urge the arm against suitable stops 121. One end of the lever arm 47 projects a short distance outward from the plane of the contact lip 116, the purpose of this construction being more fully described later. The other end of the lever arm is adapted, upon rotation thereof against the spring 120, to suitably engage a contact 48. This contact 48 is mounted upon the insulating bar 114 by a bolt 122 in such a manner that it is insulated from the metallic member 115. For 95 this purpose, a mica or other insulating strip 197 may be employed between member 115 and bar 114 so as to insulate the head of bolt 122 from member 115. 100

As a result of this construction it may be seen 105 that when the selector brush moves away from engagement with the terminal floor contact lip 116 (in an upward direction for the parts shown in Figure 5), the brush engages the projecting end of the lever arm 47 and causes rotation of 110 the lever arm so that the other end engages the contact 48. The brush then rides around the projecting end of the lever arm, whereupon the spring 120 restores the lever arm to its initial position. When the brush moves toward the terminal floor contact lip 116 (in a downward direction for the parts shown in Figure 5) the brush 115 engages the projecting end of the lever arm, and, inasmuch as the arm already is urged against the stops 121, rides around the projecting end of 120 the lever arm and then engages with contact lip 116. The upper terminal floor selector contact 46, being similar in construction and operation to the lower terminal floor selector contact 45 is 125 described only to the extent of pointing out that its lever arm and the contact with which the lever arm is adapted to engage are designated in Figure 2 as 49 and 50 respectively. 130

The invention is most readily described by a 135 description of the operation of a system embodying the invention. Such a system is shown by Figure 2. It is initially assumed that the cars are in the positions and are moving in the directions as shown by Figure 1, with the result that the selector brushes 1—44, 2—44, 3—44, and 4—44 are in corresponding positions as shown in Figure 2. It is also assumed that the knife switches 1—51, 2—51, 3—51 and 4—51 are closed so that all four cars are included in the dispatching and scheduling system; that knife switches 140

140

145

150

125 and 126 are closed, and that knife switch 130 is thrown to the left so that the blades 131 and 132 thereof engage the contacts 133 and 134 respectively. As a result, upon the closing of the 5 double bladed knife switch 127 to connect the dispatching and scheduling system to the plus and minus mains, the timing motor 20 is started. The circuit for the motor field 140 may be traced from the positive main, through the left hand 10 blade of the knife switch 127, wire 137, contacts K52 of the timing motor relay, timing motor field 140, wire 138, right hand blade of the knife switch 127, to the negative main. The circuit for the 15 motor armature 141 may be traced from the wire 137, through contacts K52 of the timing motor relay, timing motor armature 141, switch arm 143 of the timing motor speed control switch 142, one of the contacts 144 of the speed control switch, a portion of resistance 145, to wire 138. 20 The speed with which the timing motor runs is dependent upon the amount of the resistance 145 that the speed control switch 142 causes to be included in the circuit just traced. For the arrangement of the resistance 145 as shown, the less 25 resistance that is included in the motor armature circuit above traced, the faster is the speed with which the motor runs.

The closing of the knife switch 127 also results in the energization of the actuating coil DD53 30 of the down dispatching relay and of the actuating coil UU54 of the up dispatching relay. The circuit for the coil DD53 may be traced from the wire 137, through wire 146, coil DD53, knife switch 125 (which has been assumed to be closed), 35 to wire 138. The circuit for the coil UU54 may be traced from the wire 137, through wire 146, coil UU54, knife switch 126 (which has been assumed to be closed), to wire 138. The consequent operation of the down dispatching relay DD 40 causes the engagement of its contacts DD55 and the separation of its contacts DD56. The engagement of contacts DD55 prepares a circuit to the contacts D60, while the separation of contacts DD56 removes a by-pass around the contacts D61. The operation of the up dispatching 45 relay UU causes the engagement of its contacts UU57 and the separation of its contacts UU58. The engagement of contacts UU57 prepares a circuit to the contacts U62 while the separation 50 of contacts UU58 removes a by-pass around the contacts U63.

Assume that car No. 1 now arrives at the lower 55 terminal floor. The selector brush 1-44 for that car first engages the end of the lever arm 1-47, rides around it as described in connection with Figure 5, then engages with the lower terminal floor selector contact 1-45. The engagement of the selector brush 1-44 with the end of lever arm 1-47 completes a circuit from the wire 60 137, through the wire 147, knife switch 1-51, selector brush 1-44, lever arm 1-47, selector contact 1-45, actuating coil 1-LU64 of the selective up light relay for car No. 1, back contacts 1-LU65 of this relay, wire 148, back contacts 65 1-LU66, 2-LU66, 3-LU66, 4-LU66 of the selective up light relays for cars 1, 2, 3 and 4 respectively, reactance X150, to wire 138. The current flow in the circuit above traced builds up at a rate dependent upon the value of the reactance X150, and at a predetermined value of current flow the selective up light relay 1-LU operates and causes the engagement of contacts 1-LU67 and 1-LU68 and the separation of contacts 1-LU65 and 1-LU66. The engagement 70 of contacts 1-LU67 completes a holding circuit for the relay 1-LU from the actuating coil 1-LU64 direct to the wire 138. The separation of contacts 1-LU65 and 1-LU66 prevent the operation of the selective up light relays LU for all the other cars after the relay LU for the first 80 car operates. The engagement of contacts 1-LU68 prepares a circuit for the up start light 1-14 in car No. 1. Under the assumed conditions of operation the circuit for up start light 1-14 is incomplete at the contacts U-63 and 85 UU58 so that this light is not now illuminated.

It is to be noted that the transfer of contact of the selector brush 1-44 from the end of lever arm 1-47 to the lower terminal floor selector contact 1-45 as car No. 1 reaches the floor level 90 of the lower terminal floor does not break the holding circuit for the actuating coil 1-LU64 of the selective up light relay LU for car No. 1. The holding circuit for this relay when the car is at the lower terminal floor level may be traced from wire 137, through wire 147, knife switch 1-51, selector brush 1-44, selector contact 1-45, coil 1-LU64, contacts 1-LU67, to wire 138. As a result relay 1-LU is maintained operated to 95 continue its functions.

Assume that at about this time car No. 3 arrives at the upper terminal floor. The selector brush 3-44 for that car first engages the end of the lever arm 3-49, rides around it similarly as described in connection with Figure 5, then 105 engages the upper terminal floor selector contact 3-46. The engagement of the selector brush 3-44 with the end of lever arm 3-49 completes a circuit from the wire 137, through the wire 147, knife switch 3-51, selector brush 3-44, 110 lever arm 3-49, selector contact 3-46, actuating coil 3-LD70 of the selective down light relay for car No. 3, back contacts 3-LD71 of this relay, wire 151, back contacts 1-LD72, 2-LD72, 3-LD72, and 4-LD72 of the selective down light 115 relays for cars 1, 2, 3 and 4 respectively, reactance X152, to wire 138. The current flow in the circuit above traced builds up at a rate dependent upon the value of the reactance X152, and at a predetermined value of current flow the selective 120 down light relay 3-LD operates and causes the engagement of contacts 3-LD73 and 3-LD74, and the separation of contacts 3-LD71 and 3-LD72. The engagement of contacts 3-LD73 completes a holding circuit for the relay 3-LD 125 from the actuating coil 3-LD70 direct to the wire 138. The separation of contacts 3-LD71 and 3-LD72 prevent the operation of the selective down light relays LD for all the other cars after the relay LD for the third car operates. The 130 engagement of contacts 3-LD74 prepares a circuit for the down start light 3-15 in car No. 3. Under the assumed conditions of operation the circuit for down start light 3-15 is incomplete at the contacts D61 and DD56 so that this light 135 is not now illuminated.

It is to be noted that the transfer of contact of the selector brush 3-44 from the end of lever arm 3-49 to the upper terminal 3-46 as car No. 3 reaches the floor level of the upper terminal 140 floor does not break the holding circuit for the actuating coil 3-LD70 of the selective down light relay for car No. 3. The holding circuit for this relay when the car is at the upper terminal floor level may be traced from wire 137, through wire 147, knife switch 3-51, selector brush 3-44, selector contact 3-46, coil 3-LD70, contacts 3-LD73, to wire 138. As a result relay 3-LD 145 is maintained operated to continue its functions.

Assume that after the cars Nos. 1 and 3 have 150

reached the lower and upper terminals, respectively, as described above, the rotation of shaft 22 by the timing motor causes the engagement of contact bridge 25 with the stationary contacts 34 and 35, and the engagement of contact bridge 26 with the stationary contacts 36 and 37. With the illustrated setting of the arms 30 and 31 which support the contact bridges 25 and 26, the contact bridges engage their respective contacts substantially simultaneously. The engagement of contact bridge 25 with the contacts 34 and 35 completes a circuit from wire 137, through wire 146, contact 34, bridge 25, contact 35, actuating coil U75 of the up schedule relay, knife switch 126, to wire 138, for energizing the actuating coil U75 of the up schedule relay and thereupon causing the engagement of contacts U62 and U63. The up schedule relay is of the type that mechanically latches in after being operated, so that the contacts U62 and U63 are maintained in engagement after the deenergization of actuating coil U75 when the contact bridge 25 subsequently disengages from the stationary contacts 34 and 35. The engagement of contacts U62 is of no effect at the present moment, and their function will be described later. The engagement of contacts U63 completes a circuit from wire 137, through wire 147, knife switch 1-51, selector brush 1-44, selector contact 1-45, up start light 1-14, contacts 1-LU68, actuating coil FU76 of the up flicker relay, contacts FU77 of the up flicker relay, contacts U63, to wire 138, for causing the illumination of the up start light 1-14 for car No. 1. The up start light is not steady in its illumination, however, as the energization of the actuating coil FU76 of the flicker relay results in the separation of contacts FU77 to cause the breaking of the light circuit and the extinguishment of the light. As soon as the light circuit is broken by the separation of the contacts FU77, the coil FU76 is deenergized so that the contacts FU77 reengage, and thus the cycle repeats itself. In this manner the up flicker relay FU causes the up start light to flicker. The flickering up start light 1-14 is a signal to the operator of the car No. 1 to leave the lower terminal floor. The engagement of contacts U63 also completes a circuit from wire 137, through wire 147, starters' light 17 for the lower terminal floor, contacts FU77, contacts U63, to wire 138, for causing the illumination of the starters' light 17. The contacts FU77 of the up flicker relay being included in this circuit, the starters' light 17 flickers with the up start light 1-14. The flickering starters' light 17 is a signal to the starter that a car at the lower terminal floor has received a signal to start. The engagement of contact bridge 26 with the contacts 36 and 37 completes a circuit from wire 137, through wire 146, contact 36, bridge 26, contact 37, contact 133, blade 131 of the knife switch 130, actuating coil D80 of the down schedule relay, knife switch 125, to wire 138, for energizing the actuating coil D80 of the down schedule relay and thereupon causing the engagement of contacts D60 and D61. The down schedule relay is of the type that mechanically latches in after being operated so that the contacts D60 and D61 are maintained in engagement after the deenergization of actuating coil D80 when the contact bridge 26 subsequently disengages from the stationary contacts 36 and 37. The engagement of contacts D60 is of no effect at the present moment, and their function will be described later. The engagement of contacts D61 com-

pletes a circuit from wire 137, through wire 147, knife switch 3-51, selector brush 3-44, selector contact 3-46, down start light 3-15, contacts 3-LD74, actuating coil FD81 of the down flicker relay, contacts FD82 of the down flicker relay, contacts D61, to wire 138, for causing the illumination of the down start light 3-15 for car No. 3. The down start light is not steady in its illumination, however, as the energization of the actuating coil FD81 of the flicker relay results in the separation of contacts FD82 to cause the breaking of the light circuit and the extinguishment of the light. As soon as the light circuit is broken by the separation of contacts FD82, the coil FD81 is deenergized so that the contacts FD82 reengage, and thus the cycle repeats itself. In this manner, the down flicker relay FD causes the down start light to flicker. The flickering down start light 3-15 is a signal to the operator of car No. 3 to leave the upper terminal floor. The engagement of contacts D61 also completes a circuit from wire 137, through wire 147, starter's light 18 for the upper terminal floor, contacts FD82, contacts D61, to wire 138, for causing the illumination of the starter's light 18. The contacts FD82 of the down flicker relay being included in this circuit, the starter's light 18 flickers with the down start light 3-15. The flickering illumination of the starter's light 18 is a signal to the starter that a car at the upper terminal floor has received a signal to start.

Assume that in compliance with the signal given by the up start light 1-14, the operator of car No. 1 closes the car and hatchway doors and starts his car upward. The movement of the car away from the lower terminal floor results in the upward movement of the selector brush 1-44. The roller 106 of the selector brush 1-44 engages the underside of the projecting end of the lower arm 1-47 with the result that as the car moves away from the lower terminal floor the lever arm is rotated so that the other end of the lever arm engages with the contact 1-48. A circuit is thereby completed from wire 137, through wire 147, knife switch 1-51, selector brush 1-44, lever arm 1-47, contact 1-48, reset coil U83, wire 153, contacts U63 to wire 138 for energizing the reset coil U83. As a result the mechanical latch of the up schedule relay U is released so that the relay drops back to its initial position with its contacts U62 and U63 disengaged. The purpose of the disengagement of contacts U62 will be explained later. The disengagement of the contacts U63 extinguishes both the up start light 1-14 and the starter's light 17. The extinguishment of the starter's light 17 is a signal to the starter that the car which received the up start signal to start has left the lower terminal floor.

The roller 106 of the selector brush 1-44 rides around the projecting end of the lever arm 1-47 as the car continues its motion away from the lower terminal floor and then the roller disengages from the lever arm. As a result the circuit for the actuating coil 1-LU64 is broken, so that the selective up light relay 1-LU drops back to its initial position with its contacts 1-LU65 and 1-LU66 in engagement, and its contacts 1-LU67 and 1-LU68 separated. The lever arm 1-47 returns to its initial position under the action of spring 120.

Assume that in compliance with the signal given by the down start light 3-15, the operator of car No. 3 closes the car and hatchway doors

and starts his car downward. The movement of the car away from the upper terminal floor results in the downward movement of the selector brush 3-44. The roller 106 of the selector brush 6 3-44 engages with the underside of the projecting end of the lever arm 3-49 with the result that, as the car moves away from the upper terminal floor, the lever arm is rotated so that the other end of the lever arm engages with the 10 contact 3-50. The circuit is thereby completed from wire 137, through wire 147, knife switch 3-51, selector brush 3-44, lever arm 3-49, contact 3-50, reset coil D84, wire 154, contacts D61, to wire 138, for energizing the reset coil 15 D84. As a result, the mechanical latch of the down schedule relay D is released so that the relay drops back to its initial position with its contacts D60 and D61 disengaged. The purpose of the disengagement of contacts D60 will be explained later. The disengagement of the contacts D61 extinguishes both the down start light 20 3-15 and the starter's light 18. The extinguishment of the starter's light 18 is a signal to the starter that the car which received the down start signal has left the upper terminal floor. 25

The roller 106 of the selector brush 3-44 rides around the projecting end of the lever arm 3-49 as the car continues its motion away from the upper terminal floor and then the roller disengages from the lever arm. As a result, the circuit for the actuating coil 3-LD70 is broken so that the selective down light relay 3-LD drops back to its initial position with its contacts 30 3-LD71 and 3-LD72 in engagement and its contacts 35 3-LD73 and 3-LD74 separated. The lever arm 3-49 returns to its initial position under the action of spring 120.

The timing motor continues to run and thus to cause the rotation of shaft 22 as indicated by the 40 arrows. It is to be noted that with the angular spacing of the mounting arms 30, 31, and 32 illustrated in the drawings, soon after the disengagement of contact bridge 25 from stationary contacts 34 and 35 and of contact bridge 26 from stationary contacts 36 and 37, contact bridge 27 engages with stationary contacts 42 and 43. This event is of no effect under the assumed 45 conditions of operations, however, for the section of circuit which is completed by the bridge 27 terminates at the unengaged contact 136 of the knife switch 130. Subsequently, and after the shaft 22 has rotated one half of a revolution from the position in which bridge 26 was in engagement with contacts 36 and 37, the bridge 50 26 engages the stationary contacts 38 and 39. This event is also of no effect under the assumed conditions of operations, however, for the section of circuit completed by the bridge 26 terminates at the unengaged contact 135 of the knife 55 switch 130. Soon after bridge 26 disengages from the contacts 38 and 39, the bridge 27 engages with the stationary contacts 40 and 41. This event is also of no effect, however, for the section of circuit which is completed by the bridge 60 27 terminates, for one branch, at the disengaged contacts U62, and for the other branch, including contacts 134 and blade 132 of the switch 130, at the disengaged contacts D60.

The next event in time with regard to the contact bridges 25, 26 and 27 is the engagement of bridge 25 with the stationary contacts 34 and 35 and of bridge 26 with the stationary contacts 36 and 37; in other words, the reengagement of these bridges with their corresponding contacts 70 after one revolution of the shaft 22. Before such

reengagement, however, assume that car No. 2 arrives at the lower terminal floor and that car No. 4 arrives at the upper terminal floor. A sequence of operations similar to that previously described for car No. 1, transpires for car No. 2 upon its arrival at the lower terminal floor. It is believed sufficient to point out that when car No. 2 is at the lower terminal floor level the actuating coil 2-LU64 of the selective up light relay for car No. 2 is energized, contacts 2-LU65 and 2-LU66 are disengaged and contacts 2-LU67 and 2-LU68 are engaged. A sequence of operations similar to that previously described for car No. 3 transpires for car No. 4 upon its arrival at the upper terminal floor. It is believed sufficient to point out that when car No. 4 is at the upper terminal floor level the actuating coil 4-LD70 of the selective down light relay for car No. 4 is energized, contacts 4-LD71 and 4-LD72 are disengaged, and contacts 4-LD73 and 4-LD74 are engaged. Accordingly, when the contact bridge 25 now engages with the stationary contacts 34 and 35, the actuating coil U75 of the up dispatching relay is again energized, and its contacts U62 and U63 reengage. The reengagement of the contacts U62 under the present assumed conditions of operation is, as before, of no effect. The engagement of contacts U63 completes a circuit for the up start light 2-14 similar to that previously described for the up start light 100 1-14, and also completes the circuit for the starters' light 17. The up start light 2-14 and the starter's light 17 are thereupon both illuminated, and are caused to flicker by the operation of the up flicker relay FU. The flickering up 105 start light 2-14 is a signal to the operator of car No. 2 to leave the lower terminal floor while the flickering starter's light 17 is a signal to the starter that a car at the lower terminal floor has received a signal to start. When the contact 110 bridge 26 engages with the stationary contacts 36 and 37, which, with the illustrated setting of arms 30 and 31, is substantially the same time that bridge 25 engages contacts 34 and 35, the actuating coil D80 of the down dispatching relay 115 is again energized and its contacts D60 and D61 reengage. The reengagement of the contacts D60 under the present assumed conditions of operation is, as before, of no effect. The engagement of contacts D61 completes a circuit for the down 120 start light 4-15 similar to that previously described for the down start light 3-15, and also completes the circuit for the starter's light 18. The down start light 4-15 and the starter's light 125 18 are thereupon both illuminated, and are caused to flicker by the operation of the down flicker relay FD. The flickering down start light 4-15 is a signal to the operator of car No. 4 to leave the upper terminal floor, while the flickering starter's light 18 is a signal to the starter that a car at the 130 upper terminal floor has received a signal to start.

Assume now that in compliance with the signal given by the up start light 2-14, the operator of car No. 2 starts his car upward from the lower 140 terminal floor, and that in compliance with the signal given by the down start light 4-15, the operator of car No. 4 starts his car downward from the upper terminal floor. In a manner similar to that previously described for the departure of car No. 1 from the lower terminal floor, the departure of car No. 2 from the lower terminal floor resets the up schedule relay U, extinguishes the up start light 2-14 and the starter's light 17, and deenergizes the actuating coil 145 150

of the selective up light relay 2-LU to permit the contacts thereof to return to their initial positions. In a manner similar to that previously described for the departure of car No. 3 from the 5 upper terminal floor, the departure of car No. 4 from the upper terminal floor resets the down schedule relay D, extinguishes the down start light 4-15 and the starter's light 18, and de-energizes the actuating coil of the selective down 10 light relay 4-LD to permit the contacts thereof to return to their initial positions.

The timing motor continues to run, and, under the conditions of operation that have been assumed, the previously described cycle of events

- 15 after the disengagement of contact bridge 25 from the stationary contacts 34 and 35 and contact bridge 26 from stationary contacts 36 and 37 to the reengagement of these bridges with their respective stationary contacts again transpires.
- 20 It is assumed, similarly as has been previously assumed, that before the reengagement of contact bridge 25 with the stationary contacts 34 and 35 and the reengagement of contact bridge 26 with the stationary contacts 36 and 37, a car has 25 arrived at the lower terminal floor and another car has arrived at the upper terminal floor. Under normal operating conditions, car No. 3 would be the car to have arrived at this time at the lower terminal floor and car No. 1 at the 30 upper terminal floor. Accordingly, it is so assumed. There transpires for car No. 3 a cycle of events similar to that previously described while car No. 1 was at the lower terminal floor and there transpires for car No. 1 a cycle of events 35 similar to that previously described while car No. 3 was at the upper terminal floor.

Further description of the operation of the system under conditions, similar to those that have been assumed is believed unnecessary. It is 40 believed clear that when a car at each terminal floor is started away with reasonable promptness in compliance with the corresponding up start or down start signal given it, and that before the expiration of the normal time interval after the 45 giving of that start signal (as determined by a complete, continuous revolution of the shaft 22) a car again arrives at each terminal floor, the start signals are given without delay at the expiration of the normal time interval. Under these 50 conditions the start signals are given at regular intervals, and thus there is regularity in the dispatching of the cars from both terminal floors. The elevator service thus tends to be uniform, for there is normally the same number of cars on the up trip as on the down trip. This relationship among the cars may be termed as having the cars "balanced."

It may happen, for example, when a car makes more than a normal number of stops during a 60 trip, or when it is delayed for other causes, that the car has not arrived at the terminal floor by the time that it is scheduled to depart therefrom. For example, assume that car No. 1 has been delayed in its travel toward the lower terminal floor. 65 The engagement of contact bridge 25 with the stationary contacts 34 and 35 before the arrival of car No. 1 at the lower terminal floor completes a circuit for the actuating coil U75 of the up schedule relay similarly as previously described. 70 The resulting operation of the up schedule relay U causes the engagement of its contacts U62 and U63, and the mechanical latching in of the relay to maintain these contacts in engagement. The engagement of contacts U62 is of no effect at 75 the present moment. The engagement of con-

tacts U63 completes a circuit for the starter's light 17 from wire 137, through wire 147, starter's light 17 for the lower terminal floor, contacts FU77, contacts U63, to wire 138, for causing the illumination of the starter's light 17. As the car 80 is not at the lower terminal floor, with the result that its selector brush 1-44 is not in engagement with the lower terminal floor selector contact 1-45, the engagement of contacts U63 does not cause the illumination of up start light 1-14 or cause the operation of the up flicker relay FU. The contacts FU77 of the up flicker relay thus remain in engagement, so that the circuit to the starter's light 17 is uninterrupted. The resulting steady illumination of the starter's light 17 90 is a signal to the starter that a starting signal is being given to dispatch a car from the lower terminal floor, and that no car eligible to be dispatched in response thereto has arrived at that floor.

When car No. 1 arrives at the lower terminal floor and its selector brush 1-44 engages with the projecting end of the lever arm 1-47, the actuating coil of the selective up light relay 1-LU is energized to cause and maintain, among 100 other things, the engagement of its contacts 1-LU68. The details by which this is effected has been previously described. The circuit for the up start light 1-14 is thereby completed. This circuit has also been previously traced. Inasmuch as the actuating coil FU76 of the up flicker relay is energized along with the up start light 1-14, the up flicker relay operates. The resulting engagement, separation and reengagement of the contacts FU77 causes both the up 105 start light 1-14 and the starter's light 17 to flicker. This condition continues while the car remains at the lower terminal floor, it being remembered that the selective up light relay 1-LU is maintained operated while the selector 115 brush 1-44 engages the lower terminal floor selector contact 1-45. The flickering up start light 1-14 is the signal to the operator of car No. 1 to leave the lower terminal floor. The change in the illumination of the starter's light 120 17 from a steady to a flickering light is a signal to the starter that a car eligible to be dispatched has arrived at the lower terminal floor and that that car is receiving the dispatch signal to start. Both lights continue to operate in a flickering 125 fashion until, as previously described, they are extinguished upon the departure of the car from the lower terminal floor.

A similar operation occurs in the event that a car is delayed in reaching the upper terminal 130 floor. Assuming, for example, that the contact bridge 26 engages with stationary contacts 36 and 37 before the arrival of car No. 3 at the upper terminal floor, a circuit is completed for the actuating coil D80 of the down schedule relay D 135 similarly as previously described. The resulting operation of this relay causes the engagement of its contact D60 and D61 and the mechanical latching in of the relay to maintain these contacts in engagement. The engagement 140 of contacts D60 is of no effect at the present moment. The engagement of contacts D61 completes a circuit for the starter's light 18 from wire 137, through wire 147, starter's light 18, contacts FD82, contacts D61, to wire 138, for causing the illumination of the starter's light 18. As car No. 3 is not at the upper terminal floor, with the result that its selector brush 3-44 is not in engagement with the upper terminal floor selector contact 3-46, the engagement of contacts 145 150

D61 does not cause the illumination of down start light 3-15 or cause the operation of the down flicker relay FD. The contacts FD82 of the down flicker relay thus remain in engagement, 5 so that the circuit to the starter's light is uninterrupted. The resulting steady illumination of the starter's light 18 is a signal to the starter that a starting signal is being given to dispatch a car from the upper terminal floor, and that no 10 car eligible to be dispatched in response thereto has arrived at that floor.

When car No. 3 arrives at the upper terminal floor and its selector brush 3-44 engages with the projecting end of the lever arm 3-49, the 15 actuating coil of the selective down light relay 3-LD is energized to cause and maintain, among other things, the engagement of contacts 3-LD74. The details by which this is effected have been previously described. The circuit for 20 the down start light 3-15 is thereby completed. This circuit has also been previously traced. Inasmuch as the actuating coil FD81 of the down flicker relay is energized along with the down start light 3-15, the down flicker relay operates. The resulting engagement, separation, and 25 reengagement of the contacts FD82 causes both the down start light 3-15 and the starter's light 18 to flicker. This condition continues while the car remains at the upper terminal floor, it being 30 remembered that the selective down light relay 3-LD is maintained operated while the selector brush 3-44 engages the upper terminal floor selector contact 3-46. The flickering down start light 3-15 is the signal to the operator of 35 car No. 3 to leave the upper terminal floor. The change in the illumination of the starter's light 18 from a steady to a flickering light is a signal to the starter that a car eligible to be dispatched has arrived at the upper terminal floor and that 40 that car is receiving the dispatch signal to start. Both lights continue to operate in a flickering fashion until, as previously described, they are extinguished upon the departure of the car from the upper terminal floor.

45 The above described operation of the starter's lights 17 and 18 assists the starter or other official in the complete supervision of the bank of elevators. He is informed when a dispatch signal is given by the scheduling device. He is informed whether or not there is a car eligible to 50 receive this dispatch signal at the terminal floor for which the signal is given, and if there is no car eligible to receive this dispatch signal at the terminal floor, when such a car does arrive at 55 the terminal floor. He is informed all during the time a car is receiving a dispatch signal. He is also informed when the car actually leaves in response to such signal. Thus he may see whether or not the operators are starting their 60 cars away from the terminal floors with reasonable promptness after they have received the signal to start. In the system illustrated this supervision extends to both the lower and upper terminal floors. Utilization of the system in 65 conjunction with the indicators that show the positions of the cars in the elevator bank enables the starter to determine which of the cars in the bank is receiving the starting signal.

Under certain abnormal conditions of operation, 70 frequently only temporary in character, it may happen that one car may run into traffic considerably heavier than normal while the succeeding car may run into traffic considerably lighter than normal. In this event the succeeding 75 car may overtake and pass the preceding car

and be the prior of the two to arrive at the terminal floor destination. When this situation occurs, the car first arriving and causing the operation of its selective up light relay LU if the destination is the lower terminal floor, or its selective down light relay LD if the destination is the upper terminal floor, is the car to be dispatched first. This is due to the fact that the operation of the selective up light relay LU for the car first to arrive at the lower terminal floor causes the separation of its corresponding back contacts LU65 and LU66 to prevent the operation of the selective up light relay for each of the other cars, and the operation of the selective down light relay LD for the car first to arrive at the upper terminal floor causes the separation of its corresponding back contacts LD71 and LD72 to prevent the operation of the selective down light relay for each of the other cars. Accordingly, should the overtaken car arrive at the terminal floor before the overtaking car receives the dispatch signal to start, the overtaken car does not receive that dispatch signal. Only after the overtaking car has left the terminal floor, and in so doing has reset the schedule relay 100 U or D and deenergized its corresponding selective up or down light relay, and after the selective up or down light relay for the overtaken car operates, is the overtaken car able to receive a dispatch signal to start. The overtaken car is 105 then dispatched by the next succeeding dispatch signal. Thus the dispatch signal which the overtaken car receives is the next succeeding dispatch signal that is given for that terminal floor by the timing mechanism. As a result of the above described operations that occur when a car is overtaken by a succeeding car, the succeeding car is 110 moved up into the place of the overtaken car in the system, and the overtaking car is dropped back into the place of the succeeding car so that 115 regularity of elevator service in the building may be effected.

Certain other operating conditions may occur with the result that one car may be subjected to unusual delays during its run from one terminal floor to the other, and still not be overtaken by the succeeding car. In such event the car may be quite a bit behind schedule in its arrival at a terminal floor and in its departure therefrom. With the arrangement of the cars and the system 120 that has been previously described, assume that car No. 1 has been delayed in its travel toward the lower terminal floor while car No. 3 has arrived at the upper terminal floor substantially according to schedule, and departs therefrom 125 promptly upon receipt of the starting signal. As a result, the cycle of events with regard to the delayed car only, car No. 1, need be described. The engagement of contact bridge 25 with the stationary contacts 34 and 35 before the arrival of 130 car No. 1 at the lower terminal floor causes the operation of the up schedule relay U, the engagement and latching-in of contacts U62 and U63, and the illumination of the starter's light 17, all as previously explained. The contact bridge 25 then disengages from contacts 34 and 35 and, with the setting of the arms 30 and 32 that is 135 illustrated in the drawings, soon thereafter contact bridge 27 engages with the stationary contacts 42 and 43. This event is of no effect, under 140 the assumed conditions of operation wherein the knife switch 130 is thrown to the left, for the section of circuit which is completed by the contact bridge 27 terminates at the unengaged contact 145 136 of this knife switch 130. After the dis- 150

engagement of contact bridge 27 from contacts 42 and 43, substantially one-half of a revolution of timing shaft 22 ensues before bridge 27 engages with the contacts 40 and 41. Under normal operating conditions for the arrangement of the cars and the adjustment of the system that have been assumed, and allowing for average temporary delays, car No. 1 should depart from the lower terminal floor before contact bridge 27 engages with contacts 40 and 41. In the event that the car has not departed when bridge 27 engages with contacts 40 and 41 (which condition may result when the car has not yet arrived at the lower terminal floor as well as when the car has arrived at the lower terminal floor but not departed therefrom), the engagement of bridge 27 with contacts 40 and 41 completes a circuit for energizing the actuating coil K78 of the timing motor relay. This circuit may be traced from wire 137, through contacts UU57, contacts U62, stationary contact 40, contact bridge 27, stationary contact 41, actuating coil K78, to wire 138. (It is recalled that knife switch 126 is closed so that the up dispatching relay UU is operated to maintain contacts UU57 in engagement.) The resulting operation of the timing motor relay causes the separation of its contacts K52 in the timing motor feed. Accordingly, the timing motor 20 stops and the timing shaft 22 ceases to revolve. The timing is thus suspended pending the departure of the car from the lower terminal floor. This suspension aids in the readjustment of the system to the excessive delaying of car No. 1, and tends to keep the cars in the desired balanced relation. This is hereinafter more fully described. When car No. 1 eventually does depart from the lower terminal floor, its departure results in the resetting of the up schedule relay U, and thus in the restoration of contacts U62 to their initial disengaged condition. The manner by which this is effected has been previously described. The separation of contacts U62 breaks the circuit for the actuating coil K78 of the timing motor relay, and so permits the reengagement of its normally engaged contacts K52 to cause the reenergization of timing motor 20. The timing motor thereupon resumes its operation to cause the rotation of timing shaft 22, and thus to resume the normal operations of the system.

Assume the condition reverse to that above, wherein with the arrangement of the cars and the system as has been previously described, car No. 3 has been delayed in its travel toward the upper terminal floor, while car No. 1 has arrived at the lower terminal floor substantially according to schedule and departs therefrom promptly upon receipt of the starting signal. As a result, the cycle of events with regard to the delayed car only, car No. 3, need be described. The engagement of contact bridge 26 with the stationary contacts 36 and 37 before the arrival of car No. 3 at the upper terminal floor causes the operation of the down schedule relay D, the engagement and latching-in of contacts D60 and D61, and the illumination of the starter's light 18, all as previously explained. The contact bridge 26 then disengages from contacts 36 and 37, and with the setting of the arms 31 and 32 that is illustrated in the drawings, soon thereafter contact bridge 27 engages with the stationary contacts 42 and 43. This event is of no effect under the assumed conditions of operation wherein the knife switch 130 is thrown to the left, for the section of circuit which is completed by the contact bridge 27 terminates at the unengaged contact 136 of this knife switch 130. After the disengagement of contact bridge 27 from contacts 42 and 43, substantially one-half of a revolution of timing shaft 22 ensues before bridge 27 engages with the contacts 40 and 41. During the course of this one-half of a revolution contact bridge 26 engages with, and separates from, the contacts 38 and 39. This event is of no effect, however, for the section of circuit completed by the bridge 26 terminates at the unengaged contact 135 of the knife switch 130. Under normal operating conditions for the arrangement of the cars and the adjustment of the system that have been assumed, and allowing for average temporary delays, car No. 3 should depart from the upper terminal floor before contact bridge 27 engages with contacts 40 and 41. In the event that the car has not departed when bridge 27 engages with contacts 40 and 41 (which condition may result when the car has not yet arrived at the upper terminal floor as well as when the car has arrived at the upper terminal floor but not departed therefrom), the engagement of bridge 27 with contacts 40 and 41 completes a circuit for energizing the actuating coil K78 of the timing motor relay. This circuit may be traced from wire 137 through contacts DD55, contacts D60, blade 132 of knife switch 130, contact 132, stationary contact 40, contact bridge 27, stationary contact 41, actuating coil K78, to wire 138. (It is recalled that knife switch 125 is closed so that the down dispatching relay DD is operated to maintain contacts DD55 in engagement). The resulting operation of the timing motor relay causes the separation of its contacts K52 in the timing motor feed. Accordingly, the timing motor 20 stops and the timing shaft 22 ceases to revolve. The timing is thus suspended pending the departure of the car from the upper terminal floor. This suspension aids in the readjustment of the system to the excessive delaying of car No. 3 and tends to keep the cars in the desired balanced relation. This is hereinafter more fully described. When car No. 3 eventually does depart from the upper terminal floor its departure results in the resetting of the down schedule relay D, and thus in the restoration of contacts D60 to their initial disengaged condition. The manner by which this is effected has been previously described. The separation of contacts D60 breaks the circuit for the actuating coil K78 of the timing motor relay and so permits the reengagement of its normally engaged contacts K52 to cause the reenergization of the timing motor 20. The timing motor thereupon resumes its operation to cause the rotation of timing shaft 22, and thus to resume the normal operations of the system.

It was assumed for the above described suspension of operation of the timing motor, first, that there was a delay in the departure of a car from the lower terminal floor only, then secondly, that there was a delay in the departure of a car from the upper terminal floor only. It may happen, however, that there may be a delay in the departure of one car from one terminal floor while there is a delay in the departure of another car from the other terminal floor. Under such a condition, the timing may be suspended as a result of the failure of either car to depart, but the resumption of the timing is dependent upon both cars departing. This is due to the fact that with the blade 132 of knife switch 130 in engagement with contact 134, as has been assumed, the circuit for the actuating coil K78 from wire 137 to contact 40 is, on the one hand, by way of con-

tacts UU57 and U62, and on the other, by way of contacts DD55 and D60. Hence the timing motor relay K is maintained operated to keep the timing motor deenergized until both contacts U62 and D60 are caused to separate. This occurs, as previously explained, as a result of the departure of a car from each floor in response to the signals to start therefrom.

It is believed to be clear from all the foregoing that, with the assumed operating conditions, the suspension of operation of the timing motor may be effected as a result of the delayed departure of each car from the lower terminal floor in a manner similar to that just described for car No. 1, and of each car from the upper terminal floor in a manner similar to that just described for car No. 3. Thus, under the assumed conditions of operation, if any car is excessively delayed and is not overtaken by a succeeding car, with the result that no car departs from the terminal floor by a definite time interval after the time scheduled for a car to depart from that terminal floor, (which condition may result when the car has not yet arrived at the terminal floor as well as when the car has arrived at the terminal floor but not departed therefrom), the system automatically suspends timing operations. The timing operations are resumed after a car has departed from the terminal floor in response to the dispatch signal to which no car had responded at the time the timing operations were suspended. It may be noted at this point that in the event that at the time the timing operations were suspended no car had arrived at the terminal floor, the dispatch signal to start is given to the first car to arrive at the terminal floor. This car may be the delayed car, or, if the delayed car is overtaken by a succeeding car, it may be such succeeding car. At any event, the timing operations are resumed only upon the departure of a car in response to the dispatch signal. Under these conditions the system operates to automatically adjust itself to an overdelayed departure of a car and thus tends to maintain the "balanced" relation among the cars.

The situation presented by the preceding paragraph may be briefly outlined with reference to Figure 1. As therein shown, the cars are substantially evenly spaced in a figurative traffic loop extending from the lower terminal floor, up to the upper terminal floor, and back again to the lower terminal floor. With four cars included in the dispatching system, two cars are operating on the up portion of the traffic loop, and two cars on the down portion of the traffic loop. In this respect the group of cars may be considered as in "balance". Under normal operating conditions for the adjustment of the dispatching system that has been assumed, and with no excessive delays, the cars are automatically dispatched from each terminal at regular intervals of time and maintained in their "balanced" relationship without recourse to any suspension of the timing operations. In the event that a car does not depart from the terminal floor by the definite time interval after the time scheduled for a time to depart from that terminal floor, it is indicative that a foundation is being laid for possible subsequent unbalanced operation of the system. For example, if the timing should continue and a full scheduling interval should elapse after the time the schedule relay for that terminal floor had operated and no car should depart from that terminal floor during

that interval, there would then be during that interval at that terminal floor no transfer of a car from the portion of the traffic loop leading to that terminal floor, to the portion of the traffic loop leading away therefrom. Thus, there would then be three cars on one portion of the traffic loop (operating downwardly, for example) and only one car on the other portion of the traffic loop (operating upwardly, for example). When a car should then leave the terminal floor after the first full scheduling interval had elapsed, and thus, after a second scheduling interval had been started, the departure of the car would reset the schedule relay, with the result that the starting signal to the next car would depend upon the initiation of a succeeding scheduling interval. Accordingly, the opportunity is lost for dispatching a car for the interval during which no car departed. As a result the intervention of the starter would ordinarily be necessary in order to bring the cars back into "balanced" relationship. By suspending the timing operations when there arises such a situation that is conducive to produce unbalance, the arrangement according to this invention tends to maintain the "balanced" relationship.

The preceding descriptions are all based upon the inclusion of an even number of cars in the dispatching and scheduling system. In the event that it is desired to withdraw a car from the control of the system, as, for example, car No. 4, the knife switch 4-51 is opened. As an odd number of cars is now subject to the control of the system, the knife switch 130 is thrown to the right so that its blade 131 engages contact 135 and its blade 132 engages contact 136. This change is made so that the odd number of cars may be dispatched from the terminals in such a manner as to obtain a relationship among the odd number of cars that is analogous to the "balanced" relationship among an even number of cars. It is clear that when an odd number of cars is included in the system, it is not possible to have the number of cars operating on the down portion of the figurative traffic loop equal to the number of cars operating on the up portion thereof. A relationship for an odd number of cars analogous to the balanced "relationship" for an even number of cars is schematically illustrated in Figure 6. At the instant that car No. 1 is at the lower terminal floor 11 and receiving a dispatch signal to start, car No. 2 is in the upper portion of the hatchway on a down trip, and car No. 3 is in the upper portion of the hatchway on an up trip. The cars at this instant of time, which for convenience may be designated time No. 1, are schematically shown in full-line outline. At a later instant of time, designated time No. 2, when car No. 3 is at the upper terminal floor 12 and receiving a dispatch signal to start, car No. 1 is in the lower portion of the hatchway on its up trip, and car No. 2 is in the lower portion of the hatchway on its down trip. The dotted outlines of the cars show their position at time No. 2. At a still later instant of time, designated time No. 3, car No. 2 is at the lower terminal floor receiving a dispatch signal to start, while car No. 1 is in the upper portion of the hatchway on its up trip and car No. 3 is in the upper portion of the hatchway on its down trip. The positions of the cars at this time No. 3 are not shown in Figure 6. From this analysis it may be seen that during the interval between the dispatch of a car from the lower terminal floor and the dispatch of the next succeeding car therefrom,

a car is dispatched from the upper terminal floor. This is effected, with knife switch 130 thrown over to the right, as mentioned above, in the following manner.

5 The dispatch signal for cars at the lower terminal floor is initiated upon the engagement of contact bridge 25 with stationary contacts 34 and 35 similarly as previously described. The engagement of contact bridge 26 with contacts 36 10 and 37 is of no effect as the circuit partially completed thereby is open at the unengaged contact 133. During the course of a revolution of the timing shaft 22 after the engagement of bridge 25 with contacts 34 and 35, the bridge 26 engages 15 with contacts 38 and 39. This occurs, with the illustrated setting of the arms 30 and 31, in the neighborhood of half an interval after the engagement of bridge 25 with contacts 34 and 35. The engagement of bridge 26 with contacts 20 38 and 39 completes a circuit from wire 137, through wire 146, contact 38, bridge 26, contact 39, contact 135, blade 131 of knife switch 130, actuating coil D80 of the down schedule relay, to wire 138, for causing the operation of the down schedule relay and thus the initiation of the dispatch signal for a car at the upper terminal floor.

The throwing of knife switch 130 over to the right also adjusts the time-suspending function 30 of the dispatching and scheduling system to the inclusion of an odd number of cars in the system. In the event, for example, that a car fails to leave the lower terminal floor during the interval between the engagement of bridge 25 with contacts 35 34 and 35 and the engagement of bridge 27 with contacts 40 and 41, the timing motor relay K operates similarly as previously described to suspend timing operations. On the other hand, in the event that a car fails to leave the upper terminal 40 floor during the interval between the engagement of bridge 26 with contacts 38 and 39 and the engagement of bridge 27 with contacts 42 and 43, the engagement of bridge 27 with contacts 42 and 43 causes the operation of the timing motor 45 relay K to suspend timing operations in a similar manner. The circuit which is completed in the latter situation to cause the operation of the timing motor relay K may be traced from wire 137, through contacts DD55, contacts D60, blade 132 50 of knife switch 130, contact 136, contact 42, bridge 27, contact 43, actuating coil K78 of the timing motor relay, to wire 138.

Accordingly, it is believed clear from the foregoing that any number of cars may be made subject to the control of the dispatching and scheduling system upon the closing of the knife switch 55 51 for each car to be included in the system, and the throwing of knife switch 130 to the left or right depending on whether the total number of cars included is even or odd.

During certain times of the day, as for example, in the morning, the passenger traffic may be predominately from the lower terminal floor up into the building. Under these circumstances it 65 may be desirable to reduce to a minimum the period during which a car may be at the upper terminal floor waiting for the expiration of the scheduling interval after the giving of the down dispatch signal to the preceding car. In such 70 event the starter may open knife switch 125. As a result the actuating coil DD53 of the down dispatching relay is deenergized thereby effecting the engagement of its contacts DD56 and the separation of its contacts DD55. The engagement of contacts DD56 establishes a by-pass

circuit across the contacts D61 of the down schedule relay D so that the effect is the same as if these contacts of the down schedule relay were maintained in engagement. Accordingly, as soon as a car arrives at the upper terminal floor and its selective down light relay LD operates, the circuit through its down start light 15 is complete so that the car receives the down dispatch signal immediately. The separation of contacts DD55 renders the timing suspension function inoperative for the upper terminal floor so that, with the actuating coil D80 of the down schedule relay also inoperative as a result of the opening of knife switch 125, the continued rotation of timing shaft 22 is of no effect so far as the upper terminal floor is concerned.

During certain other times of the day, as for example, in the evening, the passenger traffic may be predominately from the upper floors of the building down to the lower terminal floor. Under these circumstances it may be desirable to reduce to a minimum the period during which a car may be at the lower terminal floor waiting for the expiration of the scheduling interval after the giving of the up dispatch signal to the preceding car. In such event the starter may open knife switch 126. As a result the actuating coil UU54 of the up dispatching relay is deenergized, thereby effecting the engagement of its contacts UU58 and the separation of its contacts UU57. The engagement of contacts UU58 establishes a by-pass circuit across the contacts U63 of the up schedule relay U so that the effect is the same as if these contacts of the up schedule relay were maintained in engagement. Accordingly, as soon as a car arrives at the lower terminal floor and its selective up light relay LU operates, the circuit through its up start light 14 is complete so that the car receives the up dispatch signal immediately. The separation of contacts UU57 renders the timing-suspension function inoperative for the lower terminal floor so that, with the actuating coil U75 of the up schedule relay also inoperative as a result of the opening of knife switch 126, the continued rotation of timing shaft 22 is of no effect so far as the lower terminal floor is concerned.

It is to be noted that in the event that the passenger traffic becomes extremely heavy, the starter may dispense with the scheduled interval between cars at both terminal floors by opening both knife switch 125 and knife switch 126. As a result each car receives the signal to start as soon as it arrives at a terminal floor and its selective light relay for that floor operates. In this manner the cars may be operated to give maximum service during peak traffic conditions.

Under certain conditions of operation it may happen that at the time that a car leaves a terminal floor in compliance with a signal to start, there may be more than one car remaining at that terminal floor. This situation is most apt to arise in an elevator bank having a greater number of cars than that herein illustrated. Although only a four car bank has been described, it is to be understood that the invention may readily be applied to any number of cars. Accordingly, the situation presented above is for convenience described with reference to the four car bank illustrated, and, as a matter of fact, is within the realm of possibility in a four car bank. For convenience, assume that when car No. 1 leaves the lower terminal floor, cars No. 2 and No. 3 remain at that terminal floor. The departure of car No. 1 deenergizes the selective

- up light relay 1—LU so that contacts 1—LU66 engage. The engagement of contacts 1—LU66 completes a circuit for the actuating coil 2—LU64 of the selective up light relay for car No. 2, and 5 also completes a circuit for the actuating coil 3—LU64 of the selective up light relay for car No. 3. The resulting current flow through each actuating coil builds up at a rate dependent upon the value of the reactance X150. Each selective 10 up light relay is designed to operate at a pre-determined current flow which is different from that for which the other relays are set to operate. This may be effected by a variety of means, a simple one being a different air gap 15 adjustment for each relay. Accordingly, as the current flow builds up, a value is reached sufficient to cause the operation of the selective up light relay for one car, for example, car No. 2, but as yet insufficient to cause the operation of 20 that relay for the other car, car No. 3. As a result, the selective up light relay for car No. 2 operates, which immediately, due to the separation of its contacts 2—LU66, breaks the circuit for the actuating coil of the selective light relay 25 for all other cars, including that for car No. 3. Hence only one car of those remaining at the time car No. 1 departed is made eligible to receive the next dispatch signal. In this manner only one car is ever dispatched at a time from 30 the lower terminal floor. By a similar process, for brevity not detailed, only one car is ever dispatched at a time from the upper terminal floor.
- In the event that no cars are at a terminal floor, 35 the car first to arrive and cause the operation of its selective light relay for that terminal floor is the car first to receive a dispatch signal. This is due to the fact, previously described, that the operation of the selective light relay for a car breaks 40 the circuit for the actuating coils of the selective light relays for that terminal floor for all the other cars. As a result any car that arrives subsequent thereto and before the first car has departed, does not receive the dispatch signal that 45 is given to the first car.
- It is to be noted that the scheduling interval may be lengthened or shortened by the adjustment of the speed control switch 142. This switch, as previously explained, regulates the speed with 50 which the timing motor 20 runs, and thus the speed with which the timing shaft 22 rotates.
- It is also to be noted that the arms 30, 31 and 55 32 may be set on the timing shaft 22 at other angular relationships than those shown. For example, the arm 32 may be reset on timing shaft 22 so as to increase or decrease the predetermined time after the operation of a schedule relay before the timing is suspended, in the event that no car has departed during that time. In addition, 60 the arms 30 and 31 may be set with an appreciable angular relationship between them. The effect of this latter change is to vary the relationship between the time allowed for an up trip and the time allowed for a down trip. In other words, 65 the arms 30 and 31 may be adjusted so that the time consumed for a round trip may be apportioned in varying amounts to the up trip and to the down trip. This adjustment may be made to facilitate the operation of the scheduling system to the conditions of a particular building or 70 of a particular period of time. In explanation of the manner by which the varying relationship between the up time and the down time is effected, assume for example, that the arm 31 is reasonably set back from the arm 30. The result- 75
- ing angular relationship between arms 30 and 31 may, for convenience, be designated by the set-back angle A. Consider an instant when arm 30 is in the position to dispatch a car from the lower terminal floor as the instant from which subsequent time is computed, and assume, for the moment, that only two cars, cars Nos. 1 and 3, are included in the dispatching system. At the starting time, therefore, car No. 1 is dispatched from the lower terminal floor. Subsequently, by the time represented by the set-back angle A, car No. 3 is dispatched from the upper terminal floor. After the time from the starting instant represented by one revolution of timing shaft 22, arm 30 is again in the position to dispatch a car from the lower terminal floor. At this time car No. 3 is dispatched therefrom. Subsequently, by the time represented by the set back angle A, or in other words, measuring from the starting instant, at the time represented by 360 degrees (one revolution) plus the set-back angle A, arm 31 is in the position to dispatch a car from the upper terminal floor, and accordingly, car No. 1 is dispatched therefrom. At a still later time, when arm 30 is next in position to dispatch a car from the lower terminal floor, (which event, measuring from the starting instant, is at the time represented by two revolutions of the timing shaft or 720 degrees) car No. 1 is again dispatched from the lower terminal floor. Accordingly, the round trip time, represented by 720 degrees or two revolutions of the timing shaft 22, is apportioned so that the up trip time is represented by 360 degrees (one revolution) plus the set-back angle A, and the down trip time is represented by 360 degrees (one revolution) minus the set-back angle A. When an even number of cars greater than two is included in the dispatching system, the operation is similar to that described above for two cars, except that, if the same service is to be given in each case, a round trip time for a car may be greater by a proportionate number of complete revolutions of timing shaft 122. Accordingly, the up time and the down time are correspondingly greater although their difference, (represented by twice the set-back angle, or 2A) is the same. When an odd number of cars is included in the dispatching system it may be seen that the operation is fundamentally analogous to that above described so accordingly it is not set forth. 110
- From the above outline of the effects attendant upon adjusting the arms 30, 31 and 32 upon the timing shaft, it may be desirable, under certain conditions, to have their adjustment readily subject to the control of the starter or other supervising official. In such event the timing shaft 22, with its associated contacts, driving motor and reducing gearing, may be placed so as to be conveniently accessible to the starter or such other official in addition to the other equipment which 115 may be readily accessible to such official. If desired, each arm may be connected, through the medium of a hollow shaft, for example, to a corresponding arm positioned on the exterior of a suitable panel. The timing shaft may also be arranged to extend through the panel, and be provided with suitable means to lock the exterior arms thereto, as for example, a locking nut. With such an arrangement the setting of the arms may 120 be readily subject to adjustment. 125
- Attention is directed to the fact that no mention has been made so far in regard to lights over the hatchway doors at the terminal floors. In some buildings such lights are not provided. Where such lights are provided to indicate which 130 135 140 145 150

of the cars is at the terminal floor preparatory to departing therefrom, it may be desirable to have each of such lights dependent upon the operation of the selective up or down light relay, 5 as the case may be, for the corresponding car. This may be effected by providing an extra set of forward contacts on the selective up or down light relay for each car, and arranging such extra contacts for each car in the appropriate terminal 10 floor hall light circuit of the corresponding car. With such an arrangement, in the event that two or more cars are at the terminal floor at the same time, only the terminal floor hall light for the car that has effected the operation of its selective light relay, and so for the car first to receive the next dispatch signal, is lighted. It may also be desirable to notify the operator within a car at a terminal floor that his car is the next one to be dispatched, and that passengers are being directed to his car. In such event a notification light for that terminal floor may be mounted within each car, and connected in parallel with the hall light at that terminal floor for the corresponding car. As a result of this arrangement the 15 notification light for each car is lighted at the same time that the terminal floor hall light is lighted. For simplicity, such hall lights and notification lights have been omitted in the diagram of Figure 2.

Figures 7 and 8 taken together constitute a wiring diagram of a dispatching and scheduling system that embodies certain features in addition to those embodied in the system as described with reference to the diagram of Figure 2. For ease 20 in the understanding of Figures 7 and 8, and to avoid a description of the operation thereof which would be partially repetitious of the description of operation of Figure 2, the apparatus in Figures 7 and 8 corresponding to apparatus in Figure 2 and operating in a manner similar thereto, is designated similarly as in Figure 2. Such apparatus includes the car starting lights 14 and 15 and the starters' lights 17 and 18; the timing motor 25 and its associated circuits and apparatus; the timing shaft 22, the contact bridges 25, 26 and 27 fastened thereto, the stationary contacts engaged by said contact bridges, and the circuits, switches and relays associated with said stationary contacts; the floor selector brushes; the selective light relays, the flicker relays, and the circuits and other apparatus associated therewith. In addition, the position in which such apparatus is shown in Figures 7 and 8 corresponds with the position in which such apparatus is shown in Figure 2. As a result, the preceding description of the operation of the system of Figure 2 is applicable to the system of Figures 7 and 8, with such additions and changes as are hereinafter described.

The floor selector contacts employed in the system of Figures 7 and 8 are preferably a slightly modified form of the selector contact employed in the system of Figure 2 and illustrated in Figure 5. This floor selector contact preferably employed in the system in Figures 7 and 8 is shown in Figure 9. It is similar in construction to the selector contact shown in Figure 5 except for the lever arm 47. The lever arm of the selector contact shown in Figure 9, designated 187, is formed of insulating material. Its projecting end is provided with a metallic tip 188 which is secured thereto, as by a rivet 190. The other end of the lever arm 187 is provided with a contact 191 arranged to engage with the contact 48 when the lever arm 187 is rotated out of its normal position. The contact 191 is mounted upon the lever arm 187 as by the rivet 192. An electrical connection 194 is provided to connect the metallic tip 188 with the contact 191. Insulating bushing 198 is provided for the rivet 190 so as to insulate it from the metallic tip 188 and the connection 194. As a result of this construction, the engagement of the selector brush 44 for a car with the metallic tip 188 on the lever arm 187 as such car arrives at the terminal floor for which such selector contact of Figure 9 is provided, is without effect, since the tip 188 is insulated from the member 115 and lip 116. When the car departs from such terminal floor, the selector brush 44 for such car causes the rotation of the lever arm 187 in the manner analogous to that effected for the lever arm 47 of the selector contact of Figure 5. However, before contact 191 upon the lever arm 187 engages with the contact 48, the selector brush 44 disengages from the contact lip 116. As a result, at the time a circuit is completed from the selector brush 44, by way of tip 188, connector 194, contact 191, to contact 48 there is no circuit from the selector brush 44 to the member 115. The effect of such modifications in the selector contact upon the 80 operation of the dispatching and scheduling systems will become clear from the description of operation of the system of Figures 7 and 8 which follows later.

Apparatus in Figures 7 and 8 that is additional to that shown in Figure 2 includes for each car a selector brush 160, a lower terminal floor selector contact 161, and an upper terminal floor selector contact 162. The selector brush 160 for each car is arranged so that it engages with the lower 85 terminal floor selector contact for that car when that car is at the lower terminal floor, and so that it engages with the upper terminal floor selector contact for that car when that car is at the upper terminal floor. The selector brush 160 may be 90 similar in construction to the selector brush 44. The terminal floor selector contacts 161 and 162 may be simple contact lips similar in construction to the contact lip 116. Placed in a connection between the wire 147 (connected to 95 the positive main) and the selector brush 160 for each car is a knife switch 163. The closing of knife switch 163 for each car serves to render the selector brush 160 for that car alive. If desired, the knife switches 51 and 163 for each car may 100 be arranged so that they may be operated simultaneously, due to the fact, as will be seen as the description proceeds, that these two knife switches are ordinarily opened and closed together.

From the lower terminal floor selector contact 161 for each car there is a circuit through an auxiliary set of contacts LU90 of the selective up light relay LU for the corresponding car, and through a hall light 164 at the lower terminal 105 floor for the corresponding car, to the wire 138 (connected to the negative main). As a result of this arrangement, whenever a car is at the lower terminal floor and the selective up light relay for that car is operated, the circuit for the 110 lower terminal floor hall light for that car is complete, and that hall light is illuminated. The circuit that is completed, assuming, for illustration, that car No. 1 is at the lower terminal floor and that selective up light relay 1—LU has operated, may be traced from wire 137, through wire 147, knife switch 1—163, selector brush 1—160, lower terminal floor selector contact 1—161, lower terminal floor hall light 1—164, contacts 1—LU90 of the selective up light relay, to wire 138. As 115

was described with reference to the system of Figure 2, when the selective up light relay for a car operates, that car is the car that next receives the signal to start. Accordingly, the lower terminal floor hall light for a car is illuminated only when that car is the next one to be dispatched. Thus, in the event that there should be more than one car at the lower terminal floor, prospective passengers are directed to the proper car.

From the upper terminal floor selector contact 162 for each car there is a circuit through an auxiliary set of contacts LD91 of the selective down light relay LD for the corresponding car, and through a hall light 165 at the upper terminal floor for the corresponding car, to the wire 138 (connected to the negative main). As a result of this arrangement whenever a car is at the upper terminal floor and the selective down light relay for that car is operated, the circuit for the upper terminal floor hall light for that car is complete, and that hall light is illuminated. The circuit that is completed, assuming, for illustration, that car No. 3 is at the upper terminal floor and that selective down light relay 3—LD has operated, may be traced from wire 137, through wire 147, knife switch 3—163, selector brush 3—160, upper terminal floor selector contact 3—162, upper terminal floor hall light 3—165, contacts 3—LD91 of the selective down light relay, to wire 138. As was described with reference to the system of Figure 2, when the selective down light relay for a car operates, that car is the car that next receives the signal to start. Accordingly, the upper terminal floor hall light for a car is illuminated only when that car is the next one to be dispatched. Thus, in the event, that that there should be more than one car at the upper terminal floor, prospective passengers are directed to the proper car.

If it is desired to notify the operator within a car at a terminal floor that his car is the next to be dispatched, and that prospective passengers are being directed to his car, a notification light for that terminal floor may be mounted within each car, and connected in parallel with the hall light at that terminal floor for the corresponding car. Such notification lights, 166 for the lower terminal floor, and 167 for the upper terminal floor, have been shown in dotted outline connected across the lower and upper terminal hall lights, respectively. As a result of this arrangement, the notification light for each car is lighted at the same time that the terminal floor hall light is lighted.

It is to be noted when a car is taken out of the control of the dispatching system by opening the knife switch 51 for that car, the hall and notification lights are ordinarily rendered inoperative at the same time by opening the knife switch 163 for that car.

It may be desirable, under certain conditions, to definitely prevent the departure of a car from a terminal floor until the receipt by that car of a signal to start. These conditions may arise, for example, when the operators are careless or disobedient of instructions. In the event that an operator starts his car away from the terminal floor before receiving a signal to start, not only is that car out of schedule, but unbalance, or suspension of the timing, or both, may occur. This is due to the fact that when a car departs before receiving a signal to start, the signal to start which was intended for that car is given to the next succeeding car. Thus, two cars are

started when it is the intention to start only one. Also, in the event that the next succeeding car does not depart within the definite time interval after the initiation of the signal to start intended for the preceding car, the timing operations are suspended. An arrangement for effecting definite prevention of the departure of a car from a terminal floor until the receipt by that car of a signal to start is embodied in the system of Figures 7 and 8. Electromagnetic switches shown in Figures 7 and 8 for this purpose which are additional to those previously enumerated and described with reference to Figure 2 are designated as follows:

A—Up car holding relay	90
B—Down car holding relay	
S—Car starting switch	
Y—Auxiliary up car holding relay	
Z—Auxiliary down car holding relay	95

The up car holding relay A for each car is provided with two windings, A92 and A93 wound oppositely to each other, and arranged as schematically shown in Figure 10. The construction is such that; when both coils are deenergized, the contacts A94 are in engagement; when only coil A92 is energized, the contacts A94 are separated; and when both coils A92 and A93 are energized, the contacts A94 are in engagement. The down car holding relay B for each car is similar in construction and operation to the up car holding relay A, so for conciseness no detailed description is made thereof.

The operator's control switch 13 for each car is illustrated for simplicity as mounting only the single contact 170. Also, for simplicity there is illustrated for each car only a single stationary contact 171 with which the movable contact 170 may engage upon the throwing over of the operator's control switch to start the car. Connected between the stationary contact 171 for each car and the wire 138 (connected to the negative main) is the actuating coil S88 of a car starting switch S for the corresponding car. The energization of the actuating coil of the car starting switch for a car causes, by contacts, circuits, relay and other apparatus not shown herein, the starting of that car. The energization of the car starting switch actuating coil S88 for a car upon the throwing over of the operator's control switch 13 for that car may occur, however, only when the contacts A94 and B97 of the up and down car holding relays, respectively, for that car are in engagement. It is to be understood that the contacts 170 and 171, or their equivalent, are placed in the circuit controlling the starting of the car, and thus, in push-button-controlled elevators, for example, these contacts may be placed in the starting circuits controlled by the push buttons.

A description of the operation of the apparatus from this point is believed to most readily describe the invention. When it is desired to definitely prevent the departure of the cars from the lower and the upper terminal floors until the receipt by the cars of the dispatch signals, knife switches 172 and 173 are closed. These, as with the other knife switches employed in the system, may be mounted upon the dispatch panel 16 or elsewhere so as to be readily accessible to the starter or other official. The closing of knife switch 172 completes a circuit from wire 137, through wire 174, knife switch 172, actuating coil Y175, to wire 138, for energizing the actuating coil of the auxiliary up car holding relay Y. As a result, contacts Y176, Y177, Y178, and Y179 engage to

complete a circuit from the lower terminal floor selector contact 45 for each car to a terminal of each of the coils A92 and A93 of the up car holding relay for the corresponding car. As it is assumed that at this instant there are no cars at the lower terminal floor, the engagement of contacts Y176, Y177, Y178 and Y179 is of no further effect. The closing of knife switch 173 completes a circuit from wire 137, through wire 174, knife switch 173, actuating coil Z180, to wire 138, for energizing the actuating coil of the auxiliary down car holding relay Z. As a result, contacts Z181, Z182, Z183, and Z184 engage to complete a circuit from the upper terminal floor selector contact 46 for each car to a terminal of each of the coils B95 and B96 of the down car holding relay for the corresponding car. As it is assumed that at this instant there are also no cars at the upper terminal floor, the engagement of contacts Z181, Z182, Z183 and Z184 is of no further effect. In addition, it is assumed that the dispatching and scheduling system has been adjusted, as by the closing of the knife switches 125 and 126, so that it normally operates to initiate dispatch signals for the cars at regular intervals of time. The manner by which this type of operation is effected has been previously described so is not here repeated. It is believed sufficient to note at this point that the closing of knife switches 125 and 126 results in the separation of contacts UU58 and DD56. Accordingly, the bypass circuits around contacts U63 and D61 are removed.

Consider now that car No. 1 arrives at the lower terminal floor previous to the initiation of an up dispatch signal by an operation of the up schedule relay U. Upon the arrival of car No. 1 at the lower terminal floor, the engagement of selector brush 1-44 with the lip 116 of selector contact 1-45 completes a circuit for the actuating coil 1-A92 of the up car holding relay. This circuit may be traced from wire 137, through wire 147, knife switch 1-51, selector brush 1-44, selector contact 1-45, contacts Y176, actuating coil 1-A92, to wire 138. The resulting energization of the actuating coil 1-A92 causes the separation of the contacts 1-A94, thus effectively preventing an energization of the actuating coil 1-S88 of the starting switch for car No. 1. It is to be noted that while car No. 1 remains at the floor level of the lower terminal floor the selector brush 1-44 engages with the lower terminal floor selector contact 1-45, so that the circuit for the actuating coil 1-A92 is maintained completed. As a result, the contacts 1-A94 of the up car holding relay are maintained separated while car No. 1 is at the lower terminal floor, and before the receipt of an up dispatch signal by that car, to prevent the starting of that car from the lower terminal floor.

Under the conditions assumed, wherein at the time that car No. 1 arrived at the lower terminal floor there was no other car at that terminal floor, there also results, upon the arrival of car No. 1 at the lower terminal floor, the operation of the selective up light relay 1-LU. The manner by which this operation is effected has been previously described, so is not here repeated. The operation of the selective up light relay 1-LU causes the engagement of an auxiliary pair of contacts 1-LU86 in circuit with the actuating coil 1-A93 of the up car holding relay. This event is at the present of no consequence, for contacts UU58 and U63 are both separated.

After the foregoing operations have been com-

pleted, assume that the system operates to give a starting signal to car No. 1. This, as previously described in conjunction with Figure 2, is effected by the operation of the up schedule relay U to cause the engagement of contacts U63. The engagement of contacts U63 also completes a circuit for energizing the actuating coil 1-A93 of the up car holding relay. This circuit may be traced from wire 137, through wire 147, knife switch 1-51, selector brush 1-44, terminal floor selector contact 1-45, contacts Y176, actuating coil 1-A93, contacts 1-LU86, wire 153, contacts U63, to wire 138. As a result of the energization of the actuating coil 1-A93, the contacts 1-A94 of the up car holding relay reengage, thus enabling the operator of car No. 1 to start his car. It may thus be seen that the departure of car No. 1 from the lower terminal floor is prevented until the receipt by that car of a signal to start.

The departure of car No. 1 first results in the separation of the selector brush 1-44 from the selector contact 1-45. The circuit to the two actuating coils 1-A92 and 1-A93 is therefore broken to cause the deenergization of both of these two coils simultaneously, so that the contacts 1-A94 of the up car holding relay remain in engagement while the car departs from the lower terminal floor. The separation of selector brush 1-44 from selector contact 1-45 also breaks the circuit for the actuating coil 1-LU64 of the selective up light relay, so that this relay returns to its initial deenergized position. The starting light 1-14 is thus extinguished by the separation of contacts 1-LU68. After the selector brush 1-44 separates from selector contact 1-45, the continued motion of car No. 1 from the lower terminal floor causes the rotation of lever arm 1-187 so that the contact 1-191 thereon engages with the contact 1-48. At this time the selector brush 1-44 is in engagement with the metallic tip 1-188 mounted upon the end of the lever arm 1-187, so that there is established a circuit for the reset coil U83 of the up schedule relay which may be traced from wire 137, through wire 147, knife switch 1-51, selector brush 1-44, metallic tip 1-188, connector 1-194, contact 1-191, contact 1-48, reset coil U83, wire 153, contacts U63 to wire 138. The consequent resetting of the up schedule relay U results in the separation of its contacts U62 and U63. The separation of the contacts U62 effects the same operations as was described for these contacts in Figure 2. The separation of the contacts U63 effects the same operations as described for these contacts in Figure 2 with the exception of such differences as have been set forth above. After the car has travelled sufficiently far from the lower terminal floor that the selector brush 1-44 has rolled around the tip 1-188 of the lever arm 1-187 and disengaged therefrom, the lever arm 1-187 returns to its initial position under the action of spring 1-120. It is to be noted that while the car is away from the lower terminal floor, both actuating coils of the up car holding relay A remain completely deenergized, with the result that contacts 1-A94 remain in engagement while the car is away from the lower terminal floor. The up car holding relay A is therefore unable to prevent the starting of the car from any floor other than the lower terminal floor.

Consider that in the neighborhood of the time that car No. 1 arrives at the lower terminal floor, car No. 3 arrives at the upper terminal floor. Also, assume that car No. 3 arrives at the upper

terminal floor previous to the initiation of a down dispatch signal by an operation of the down schedule relay D. Upon the arrival of car No. 3 at the upper terminal floor, the engagement of selector brush 3-44 with the lip 116 of selector contact 3-46 completes a circuit for the actuating coil 3-B95 of the down car holding relay. This circuit may be traced from wire 137, through wire 147, knife switch 3-51, selector brush 3-44, selector contact 3-46, contacts Z183, actuating coil 3-B95, to wire 138. The resulting energization of the actuating coil 3-B95 causes the separation of the contacts 3-B97, thus effectively preventing an energization of the actuating coil 15 3-S88 of the starting switch for car No. 3. It is to be noted that while car No. 3 remains at the floor level of the upper terminal floor the selector brush 3-44 engages with the upper terminal floor selector contact 3-46, so that the circuit for 20 the actuating coil 3-B95 is maintained completed. As a result, the contacts 3-B97 of the down car holding relay are maintained separated while car No. 3 is at the upper terminal floor, and before the receipt of a down dispatch signal by 25 that car, to prevent the starting of that car from the upper terminal floor.

Under the conditions assumed, wherein at the time that car No. 3 arrives at the upper terminal floor there was no other car at that terminal floor, 30 there also results, upon the arrival of car No. 3 at the upper terminal floor, the operation of the selective down light relay 3-LD. The manner by which this operation is effected has been previously described, so is not here repeated. The 35 operation of the selective down light relay 3-LD causes the engagement of an auxiliary pair of contacts 3-LD87 in circuit with the actuating coil 3-B96 of the down car holding relay. This event is, at the moment, of no consequence, for 40 contacts DD56 and D61 are both separated.

After the foregoing operations have been completed, assume that the system operates to give a starting signal to car No. 3. This, as previously described in conjunction with Figure 2, is effected 45 by the operation of the down schedule relay D to cause the engagement of contacts D61. The engagement of contacts D61 also completes a circuit for energizing actuating coil 3-D96 of the down car holding relay. This circuit may be traced 50 from wire 137, through wire 147, knife switch 3-51, selector brush 3-44, terminal floor selector contact 3-46, contacts Z183, actuating coil 3-B96, contacts 3-LD87, wire 154, contacts D61, to wire 138. As a result of the energization of 55 the actuating coil 3-B96, the contacts 3-B97 of the down car holding relay engage, thus enabling the operator of car No. 3 to start his car. It may thus be seen that the departure of car 60 No. 3 from the upper terminal floor is prevented until the receipt by that car of a signal to start.

The departure of car No. 3 first results in the separation of the selector brush 3-44 from the selector contact 3-46. The circuit to the two actuating coils 3-B95 and 3-B96 is therefore broken to cause the deenergization of both of these two coils simultaneously, so that the contacts 3-B97 of the down car holding relay remain in engagement while the car departs from the upper terminal floor. The separation of selector brush 3-44 from selector contact 3-46 also breaks the circuit for the actuating coil 3-LD70 of the selective down light relay, so that this relay returns to its initial deenergized position. The starting light 3-15 is thus extinguished by 75 the separation of contacts 3-LD87. After the

selector brush 3-44 separates from selector contact 3-46, the continued motion of car No. 3 from the upper terminal floor causes the rotation of lever arm 3-189 so that the contact 3-191 thereon engages with the contact 3-50. At this time 80 the selector brush 3-44 is in engagement with the metallic tip 3-188 mounted upon the end of the lever arm 3-189, so that there is established a circuit for the reset coil D84 of the down schedule relay which may be traced from wire 137, through wire 147, knife switch 3-51, selector brush 3-44, metallic tip 3-188, connector 3-194, contact 3-191, contact 3-50, reset coil D84, wire 154, contacts D61 to wire 138. The consequent resetting of the down schedule relay 85 results in the separation of its contacts D60 and D61. The separation of contacts D60 effects the same operations as was described for these contacts in Figure 2. The separation of the contacts D61 effects the same operations as was described for these contacts in Figure 2 with the exception of such differences as have been set forth above. After the car has travelled sufficiently far from the lower terminal floor that the selector brush 3-44 has rolled around the tip 100 3-188 of the lever arm 3-189 and disengaged therefrom, the lever arm 3-189 returns to its initial position under the action of spring 3-120. It is to be noted that while the car is away from the upper terminal floor, both actuating coils of 105 the down car holding relay B remain completely deenergized, with the result that contacts 3-B97 remain in engagement while the car is away from the upper terminal floor. The down car holding relay B is therefore unable to prevent the starting 110 of the car from any floor other than the upper terminal floor.

The manner by which each of the other cars is definitely prevented from departing from the lower terminal floor until the receipt by that car 115 of an up dispatch signal is analogous to that detailed above for car No. 1, and so for conciseness is not described. Similarly, the manner by which each of the other cars is definitely prevented from departing from the upper terminal 120 floor until the receipt by that car of a down dispatch signal is analogous to that detailed above for car No. 3, and so for conciseness is not described.

In the event that a car arrives at a terminal 125 floor after the initiation of a dispatch signal by the schedule relay for that terminal floor, it will be recalled from the operation of the system as described for Figure 2 that the dispatch signal is given to the car immediately upon its arrival at that terminal floor. As a consequence the contacts of the car holding relay for that car, should they separate at all, immediately reengage to enable the operator of the car to immediately start his car.

In the event that a car arrives at a terminal 130 floor when there is another car already at the terminal floor, one actuating coil of the car holding relay for the arriving car for that terminal floor is energized upon the arrival of the arriving 140 car so that the contacts of the car holding relay for that car separate to prevent starting that car away therefrom. It is to be recalled that not until the car that was already at the terminal floor has departed, and the selective light relay 145 for the succeeding car has operated, is the succeeding car made eligible to receive a signal to start. Even then, however, it is to be noted, that not until the signal to start is actually given 150

to this succeeding car is the operator thereof enabled to start his car.

The preceding outlines of operation have been based upon an initial assumption that the knife switches 125 and 126 were closed, with the result that contacts UU58 and DD56 were both separated to remove the bypass circuits around contacts U63 and D61, respectively. The operations of the system when either or both knife switches 125 and 126 are open, with the result that one or the other, or both, of the contacts U63 and D61 are bypassed, so that the cars are dispatched from one or the other, or both, of the terminal floors, respectively, immediately upon their arrival at such floors, are believed to be readily comprehensible from the foregoing descriptions, together with the description of the operations of the system under these conditions as previously described with reference to Figure 2. For conciseness, therefore, such operations are not here described.

In the event that it is desired not to prevent the departure of the cars from the lower and upper terminal floors until the receipt by the cars of the dispatch signals, the knife switches 172 and 173 may be opened. As a result contacts Y176, Y177, Y178 and Y179, and contacts Z181, Z182, Z183 and Z184 each separate to prevent the energization of the two actuating coils of both the up and down car holding relays for each car. If it is desired to prevent the departure of the cars from only the lower terminal floor until the receipt by the cars at that floor of the dispatch signals, only knife switch 172 may be closed so that only the up car holding relays are rendered effective. If it is desired to prevent the departure of the cars from only the upper terminal floor until the receipt by the cars at that floor of the dispatch signals, only knife switch 173 may be closed so that only the down car holding relays are rendered effective.

It may thus be seen that the dispatching and scheduling systems as provided by this invention are capable of operating readily under numerous and various operating conditions that arise in elevator systems.

Attention is directed to the fact that when the cars are being dispatched at regular time intervals by the system either of Figure 2 or of Figures 5 and 8, the car eligible to receive the next dispatch signal from the lower or upper terminal floor may be ordered to start therefrom, without waiting for the expiration of the scheduling interval, by opening the knife switch 126 for the lower terminal floor, or knife switch 125 for the upper terminal floor. This operation is due to the previously explained by-pass circuit formed around the schedule relay contacts U63 or D61, as the case may be, as a result of the opening of knife switch 126 or 125. Such advance starting of cars may be utilized by the starter for securing "balance" among the cars in the event that the cars are not in "balance" or for such other reasons as the starter sees fit.

It is to be noted that, if so desired, audible signals may be used in place of visual signals, or, audible signals may be used in addition to visual signals. In either case, the audible signals may be single stroke or continuous stroke gongs.

It is to be understood that although the illustrated arrangements employ only one starter's light for each terminal floor as the visual means by which different signals may be given to the starter for indicating to him different conditions at a terminal floor, several independent starter's

lights may be used, each to indicate a single condition at the terminal floor. Thus, for example, the flicker relay may be removed; a second starter's light may be provided for the terminal floor and be connected in parallel with the first starter's light, already provided; a dispatch-signal-receiving relay may be provided having its actuating coil connected where the actuating coil of the flicker relay was connected; and the forward contacts of this dispatch-signal-receiving relay may be inserted in the circuit of the second starter's light. As a result of these provisions, the first starter's light lights up with a steady illumination when a dispatch signal is initiated by the system, regardless of whether or not a car is at hand eligible to receive that dispatch signal, and the second starter's light lights up with a steady illumination when a car has arrived at the terminal floor and is receiving the dispatch signal. Hence, the illumination of the first starter's light only is a signal that a dispatch signal is being given, but no car is at hand to receive it; the change to an illumination of both the first and second starter's lights is a signal that a car has arrived and is receiving the dispatch signal; and the continued illumination of both the first and second starter's lights is a signal that the car has not left in response to the order to start.

It is also to be understood that, if desired, the selector contact illustrated in Figure 9 may be employed in the system of Figure 2. Similarly, the selector contact illustrated in Figure 5 may be employed in the system of Figures 7 and 8, although, as previously explained, it is preferred in the latter system to employ the selector contact illustrated in Figure 9.

It is to be noted that in both of the systems illustrated, the resetting of the scheduling relays is accomplished only upon the actual movement of the cars from the terminal floors. If desired, however, the resetting may be effected in other manners so long as it is accomplished by an operation coincident to the starting of the cars from the terminal floors. Thus, for example, the resetting may be effected upon the completion of the circuit for starting the car from the terminal floor, or upon the release of the hoisting motor brake. Preferably, however, the resetting is effected upon the actual movement of the cars from the terminal floors in the manner herein described.

Attention is also directed to the fact that the roller selector brush shown in detail in Figure 5 is adaptable for use generally as a selector brush wherever it is desired to have but little wear of the contacting body and to insure a good contact being made.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In a dispatching and scheduling system for a plurality of elevator cars; a dispatch floor; a starting signal for dispatching each of said cars from said dispatch floor; mechanism adapted upon each operation to cause the giving of a starting signal to one of said cars at said dispatch floor; means for causing said mechanism

normally to operate at regular intervals of time; and means controlling said mechanism, and operable, in the event that no car leaves said dispatch floor after an operation of said mechanism 5 and before a predetermined time after such operation, to suspend the operation of said mechanism.

2. In a dispatching and scheduling system for a plurality of elevator cars; a dispatch floor; a starting signal for dispatching each of said cars from said dispatch floor; operating mechanism for said starting signals; means for causing said mechanism to operate a starting signal for only one of said cars that may be at said dispatch floor, to the exclusion of all other cars, upon each successive operation of said mechanism; means for causing said mechanism normally to operate to give said starting signals for said cars at regular intervals of time; and means for delaying the 10 operation of said mechanism in the event that prior to the giving of a starting signal to a car at said dispatch floor the car that received the preceding starting signal to leave said dispatch floor has not responded to said preceding starting signal.

3. In a dispatching and scheduling system for a plurality of elevator cars; a dispatch floor; a starting signal for dispatching each of said cars from said dispatch floor; mechanism adapted upon each operation to cause the giving of a starting signal to one of said cars at said dispatch floor; means for causing said mechanism normally to operate at regular intervals of time; and responsive to the non-departure of a car from said dispatch floor, during the interval from the time said mechanism operates to cause the giving of a starting signal to a predetermined time thereafter, to delay the operation of said mechanism at least until a car departs from said dispatch floor.

4. In a dispatching and scheduling system for a plurality of elevator cars; a dispatch floor; a starting signal for dispatching each of said cars from said dispatch floor; operating mechanism for said starting signals; means for causing said mechanism to operate a starting signal for only one of said cars that may be at said dispatch floor, to the exclusion of all other cars, upon each successive operation of said mechanism; means for causing said mechanism normally to operate to give said starting signals for said cars at regular intervals of time; and means responsive to the non-departure of a car at said dispatch floor that has received a starting signal, prior to the giving of a subsequent starting signal to another car, for delaying the operation of said mechanism at least until said first car departs.

5. In a dispatching and scheduling system for a plurality of elevator cars; a dispatch floor; a starting signal for dispatching each of said cars from said dispatch floor; mechanism adapted upon each operation to cause the giving of a starting signal to one of said cars at said dispatch floor; timing means for causing said mechanism normally to operate at regular intervals of time; means, operable at a predetermined time after said mechanism operates to cause the giving of a starting signal, adapted to cause said timing means to suspend operation; a plurality of devices, one for each of said cars, each device being operable upon the departure of its corresponding car from said dispatch floor; and means responsive to the operation of one of said devices, as a result of the departure from said dispatch floor of the car corresponding thereto, to render

said timing suspending means ineffective until said mechanism operates to cause the giving of another starting signal.

6. In a dispatching and scheduling system for a plurality of elevator cars; a dispatch floor; a starting signal for dispatching each of said cars from said dispatch floor; operating mechanism for said starting signals; means for causing said mechanism to operate a starting signal for only one of said cars that may be at said dispatch floor, to the exclusion of all other cars, upon each successive operation of said mechanism; timing means for causing said mechanism normally to operate to give said starting signals for said cars at regular intervals of time; means, operable at a predetermined time after said mechanism operates to cause the giving of a starting signal to a car, to cause said timing means to suspend operation; a plurality of devices, one for each of said cars, each device being operable upon the departure of its corresponding car from said dispatch floor; and means, responsive to the operation of the device for the car for which the starting signal has been given, to render said timing suspending means ineffective at least until said mechanism operates to cause the giving of a starting signal to another car.

7. In a dispatching and scheduling system for a plurality of elevator cars; a dispatch floor; a plurality of starting signals, one for each of said cars, for dispatching said cars from said dispatch floor; operating mechanism for said starting signals; means for causing said mechanism to give a starting signal for one of said cars at said dispatch floor to the exclusion of all other cars upon each successive operation thereof; timing means for causing said mechanism normally to operate to give starting signals at regular intervals of time; and means for maintaining the starting signal, when once given by said mechanism, until a car departs from said dispatch floor.

8. In a dispatching and scheduling system for a plurality of elevator cars; a dispatch floor; a start signal for each car for dispatching the cars from said dispatch floor; means responsive to the arrival of any car at said dispatch floor, in the event no other car is present at said dispatch floor, to render the start signal for such arrived car operable to the exclusion of the start signals for all the other cars; timing mechanism normally operating continuously to measure off regular scheduling intervals for the dispatch of cars from said dispatch floor; switching mechanism actuated by said timing mechanism upon the expiration of each scheduling interval; means responsive to said switching mechanism, when said switching mechanism is actuated by said timing mechanism, to cause the giving of the start signal for such one car present at said dispatch floor with its start signal operable, and, in the event no car is present at said dispatch floor with its start signal operable at the time said switching mechanism is actuated, to cause the giving of the start signal to the first car arriving at said dispatch floor and having its start signal rendered operable; and means controlling said timing mechanism, and operable in the event that no car leaves said dispatch floor after said timing mechanism actuates said switching mechanism and before a predetermined time thereafter, to suspend the operation of said timing mechanism.

9. In a dispatching and scheduling system for a plurality of elevator cars; a lower and an upper

- dispatch floor; starting signals for said cars for dispatching said cars from said dispatch floors; means responsive to the arrival of each car at the lower and at the upper dispatch floor, in the event no other cars are present at the dispatch floors at which such cars arrive at the time of their respective arrivals thereat, to render operable starting signals for such arrived cars for dispatching such arrived cars from said dispatch floors; means responsive to the operation of said preceding means to render ineffective the starting signals for dispatching all other cars from the dispatch floors at which such cars have arrived; mechanism adapted upon each operation to cause the giving of the operable starting signal for a car which is at the lower dispatch floor for dispatching such car upwardly therefrom and to cause the giving of the operable starting signal for a car which is at the upper dispatch floor for dispatching such car downwardly therefrom; means for causing said mechanism normally to operate at regular intervals of time; and means controlling said mechanism, and operable in the event that by a predetermined time after said mechanism operates a car has failed to leave either of said dispatch floors, to suspend the operation of said mechanism.
10. In a dispatching and scheduling system for a plurality of elevator cars, a lower and an upper dispatch floor; starting signals for said cars for dispatching said cars from said dispatch floors; means responsive to the arrival of each car at the lower and at the upper dispatch floor, in the event no other car is present at the dispatch floor at which such car arrives at the time of its arrival thereat, to render operable a starting signal for dispatching such arrived car from said dispatch floor; means responsive to the operation of said preceding means to render ineffective the starting signals for dispatching all other cars from the dispatch floor at which such car has arrived; mechanism adapted upon each operation to cause the giving of the operable starting signal for a car which is at the lower dispatch floor for dispatching such car upwardly therefrom and to cause the giving of the operable starting signal for a car which is at the upper dispatch floor for dispatching such car downwardly therefrom; means for causing said mechanism normally to operate at regular intervals of time; and means for delaying the operation of said mechanism in the event that prior to an operation of said mechanism for causing the giving of a starting signal to each of two cars, one at the lower dispatch floor and the other at the upper dispatch floor, both of the two cars that received the preceding starting signals as a result of the preceding operation of said mechanism have not responded to said preceding starting signals.
11. In a dispatching and scheduling system for a plurality of elevator cars; a lower and an upper dispatch floor; starting signals for said cars for dispatching said cars from said dispatch floors; mechanism operable to cause the giving of a starting signal to but one of such cars that may be at the lower dispatch floor; means for causing said mechanism normally to operate to cause the giving of starting signals to cars at the lower dispatch floor at regular intervals of time; mechanism operable to cause the giving of a starting signal to but one of said cars that may be at the upper dispatch floor; means for causing said second named mechanism to operate at a predetermined time after the operation of

- said first named mechanism; and means controlling said first named mechanism, and operable in the event that by a certain time after said predetermined time the starting signals for the cars at both dispatch floors have been unresponded to, to delay the giving of other starting signals until said starting signals for the cars at both dispatch floors have been responded to.
12. In a dispatching and scheduling system for a plurality of elevator cars; a lower and an upper dispatch floor; starting signals for said cars for dispatching said cars from said dispatch floors; mechanism adapted upon each operation to cause the giving of a starting signal to one of said cars at said lower dispatch floor and to another one of said cars at said upper dispatch floor; timing means for causing said mechanism normally to operate at regular intervals of time; means operable at a predetermined time after said mechanism operates to cause the giving of a starting signal to a car at the lower dispatch floor and to another car at the upper dispatch floor, adapted to cause said timing means to suspend operation; a plurality of devices, one for each of said cars for each of said dispatch floors, each device being operable upon the departure of its associated car from the dispatch floor for which it is provided; and means, responsive to the operation of one of said devices for the lower dispatch floor at any time after the giving of a starting signal to a car at said lower dispatch floor and before said predetermined time, together with the operation of one of said devices for the upper dispatch floor at any time after the giving of a starting signal to a car at said upper dispatch floor and before said predetermined time, for causing said timing suspending means to be ineffective.
13. In a dispatching and scheduling system for a plurality of elevator cars; a lower and an upper dispatch floor; starting signals for said cars for dispatching said cars from said dispatch floors; mechanism adapted upon each operation to cause the giving of a starting signal to one of said cars at said lower dispatch floor and to another one of said cars at said upper dispatch floor; timing means for causing said mechanism normally to operate at regular intervals of time; means, operable at a predetermined time after said mechanism operates to cause the giving of a starting signal to a car at the lower dispatch floor and to another car at the upper dispatch floor, adapted to cause said timing means to suspend operation; a plurality of devices, one for each of said cars for each of said dispatch floors, each device being operable upon the departure of its associated car from the dispatch floor for which it is provided; and means, responsive to the operation of the device for the lower dispatch floor corresponding to the car at said lower dispatch floor to which a starting signal has been given, provided such operation of said device for the lower dispatch floor occurs after the giving of a starting signal to said car at said lower dispatch floor and before said predetermined time, together with the operation of the device for the upper dispatch floor corresponding to the car at said upper dispatch floor to which a starting signal has been given, provided such operation of said device for the upper dispatch floor occurs after the giving of a starting signal to said car at said upper dispatch floor and before said predetermined time, for causing said timing suspending means to be ineffective at least until the succeeding operation of said mechanism.

14. In a dispatching and scheduling system for a plurality of elevator cars; a lower and an upper dispatch floor; starting signals for said cars for dispatching said cars from said dispatch floors; operating mechanism for said starting signals operable for the lower and the upper dispatch floors; means for causing said mechanism to operate a starting signal for only one of said cars at said lower dispatch floor to the exclusion of all other cars upon each successive operation thereof for the lower dispatch floor; means for causing said mechanism to operate a starting signal for only one of said cars at said upper dispatch floor to the exclusion of all other cars upon each successive operation thereof for the upper dispatch floor; means for causing said mechanism normally to operate to give said starting signals for the lower and the upper dispatch floors at regular intervals of time; and means for suspending the operation of said mechanism in the event that prior to the giving of a starting signal to a car at one dispatch floor the car that received the preceding starting signal to leave the lower dispatch floor and the car that received the preceding starting signal to leave the upper dispatch floor have each not responded to said preceding starting signals. 80

15. In a dispatching and scheduling system for a plurality of elevator cars; a lower and an upper dispatch floor; an up start signal and a down start signal for each of said cars; mechanism for the lower dispatch floor adapted upon each operation to cause the giving of an up start signal to one of said cars at said lower dispatch floor; mechanism for the upper dispatch floor adapted upon each operation to cause the giving of a down start signal to one of said cars at said upper dispatch floor; means for causing both of said mechanisms normally to operate at regular intervals of time; and means for causing a suspension in the operation of both of said mechanisms either in the event that between the instant an up start signal is given and a definite instant after such up start signal and a down start signal are given a car has not left the lower dispatch floor, or in the event that between the instant a down start signal is given and said definite instant a car has not left the upper dispatch floor. 90

16. In a dispatching and scheduling system for a plurality of elevator cars; a lower and an upper dispatch floor; starting signals for said cars for dispatching said cars from said dispatch floors; mechanism operable to cause the giving of a starting signal to but one of such cars that may be at the lower dispatch floor; means for causing said mechanism normally to operate to cause the giving of starting signals to cars at the lower dispatch floor at regular intervals of time; mechanism operable to cause the giving of a starting signal to but one of said cars that may be at the upper dispatch floor; means for causing said second named mechanism to operate at a predetermined time after the operation of said first named mechanism; means operable, in the event that no car is present at said lower dispatch floor when said first named mechanism operates, to cause the starting signal then attempted to be given to be given to a car which thereafter arrives at said lower dispatch floor immediately upon the arrival of said subsequently arriving car; means operable, in the event that no car is present at said upper dispatch floor when said second named mechanism operates, to cause the starting signal then attempted to be given to be given to a car which thereafter arrives at said upper dispatch floor immediately upon the arrival of said subsequently arriving car; and means responsive to the arrival of any car at the lower dispatch floor, in the event that no car is present at said upper dispatch floor, to cause the giving of starting signals to all the other cars at the lower dispatch floor. 100

17. In a dispatching and scheduling system for a plurality of elevator cars, a lower and an upper dispatch floor; starting signals for said cars for dispatching said cars from said dispatch floors; means responsive to the arrival of each car at the lower and at the upper dispatch floor, in the event no other cars are present at the dispatch floors at which such cars arrive at the time of their respective arrivals thereat, to render operable starting signals for such arrived cars for dispatching such arrived cars from said dispatch floors; means responsive to the operation of said preceding means to render ineffective the starting signals for dispatching all other cars from the dispatch floors at which such cars have arrived; mechanism adapted upon each operation to cause the giving of the operable starting signal for a car which is at the lower dispatch floor for dispatching such car upwardly therefrom and to cause the giving of the operable starting signal for a car which is at the upper dispatch floor for dispatching such car downwardly therefrom; means operable, in the event that no car is present at said lower dispatch floor when said mechanism operates to cause the giving of a starting signal to dispatch a car upwardly from said lower dispatch floor, to cause the starting signal then attempted to be given to be given to a car which thereafter arrives at said lower dispatch floor immediately upon the arrival of said subsequently arriving car; means operable, in the event that no car is present at said upper dispatch floor when said mechanism operates to cause the giving of a starting signal to dispatch a car downwardly from said upper dispatch floor, to cause the starting signal then attempted to be given to be given to a car which thereafter arrives at said upper dispatch floor immediately upon the arrival of said subsequently arriving car; means for causing said mechanism normally to operate at regular intervals of time; and means controlling said mechanism, and operable in the event that by a predetermined time after said mechanism operates a car has failed to leave either of said dispatch floors, to suspend the operation of said mechanism. 110

18. In a dispatching and scheduling system for a plurality of elevator cars; a lower dispatch floor and an upper dispatch floor; an up start signal for each car for dispatching the cars from the lower dispatch floor; a down start signal for each car for dispatching the cars from the upper dispatch floor; means responsive to the arrival of any car at the lower dispatch floor, in the event no other car is present at such lower floor, to render the up start signal for such arrived car operable to the exclusion of the up start signals for all the other cars; means responsive to the arrival of any car at the upper dispatch floor, in the event no other car is present at such upper floor, to render the down start signal for such arrived car operable to the exclusion of the down start signals for all the other cars; timing mechanism normally operating continuously to measure off regular scheduling intervals for both the 120

19. In a dispatching and scheduling system for a plurality of elevator cars; a lower and an upper dispatch floor; starting signals for said cars for dispatching said cars from said dispatch floors; mechanism operable to cause the giving of a starting signal to but one of such cars that may be at the lower dispatch floor; means for causing said mechanism normally to operate to cause the giving of starting signals to cars at the lower dispatch floor at regular intervals of time; mechanism operable to cause the giving of a starting signal to but one of said cars that may be at the upper dispatch floor; means for causing said second named mechanism to operate at a predetermined time after the operation of said first named mechanism; means operable, in the event that no car is present at said lower dispatch floor when said first named mechanism operates, to cause the starting signal then attempted to be given to be given to a car which thereafter arrives at said lower dispatch floor immediately upon the arrival of said subsequently arriving car; means operable, in the event that no car is present at said upper dispatch floor when said second named mechanism operates, to cause the starting signal then attempted to be given to be given to a car which thereafter arrives at said upper dispatch floor immediately upon the arrival of said subsequently arriving car; and means responsive to the arrival of any car at the lower dispatch floor, in the event that no car is present at said upper dispatch floor, to cause the giving of starting signals to all the other cars at the lower dispatch floor. 130

20. In a dispatching and scheduling system for a plurality of elevator cars; a lower and an upper dispatch floor; starting signals for said cars for dispatching said cars from said dispatch floors; means responsive to the arrival of each car at the lower and at the upper dispatch floor, in the event no other cars are present at the dispatch floors at which such cars arrive at the time of their respective arrivals thereat, to render operable starting signals for such arrived cars for dispatching such arrived cars from said dispatch floors; means responsive to the operation of said preceding means to render ineffective the starting signals for dispatching all other cars from the dispatch floors at which such cars have arrived; mechanism adapted upon each operation to cause the giving of the operable starting signal for a car which is at the lower dispatch floor for dispatching such car upwardly therefrom and to cause the giving of the operable starting signal for a car which is at the upper dispatch floor for dispatching such car downwardly therefrom; means operable, in the event that no car is present at said lower dispatch floor when said mechanism operates to cause the giving of a starting signal to dispatch a car upwardly from said lower dispatch floor, to cause the starting signal then attempted to be given to be given to a car which thereafter arrives at said lower dispatch floor immediately upon the arrival of said subsequently arriving car; means operable, in the event that no car is present at said upper dispatch floor when said mechanism operates to cause the giving of a starting signal to dispatch a car downwardly from said upper dispatch floor, to cause the starting signal then attempted to be given to be given to a car which thereafter arrives at said upper dispatch floor immediately upon the arrival of said subsequently arriving car; means for causing said mechanism normally to operate at regular intervals of time; and means controlling said mechanism, and operable in the event that by a predetermined time after said mechanism operates a car has failed to leave either of said dispatch floors, to suspend the operation of said mechanism. 145

21. In a dispatching and scheduling system for a plurality of elevator cars; a lower and an upper dispatch floor; starting signals for said cars for dispatching said cars from said dispatch floors; mechanism operable to cause the giving of a starting signal to but one of such cars that may be at the lower dispatch floor; means for causing said mechanism normally to operate to cause the giving of starting signals to cars at the lower dispatch floor at regular intervals of time; mechanism operable to cause the giving of a starting signal to but one of said cars that may be at the upper dispatch floor; means for causing said second named mechanism to operate at a predetermined time after the operation of said first named mechanism; means operable, in the event that no car is present at said lower dispatch floor when said first named mechanism operates, to cause the starting signal then attempted to be given to be given to a car which thereafter arrives at said lower dispatch floor immediately upon the arrival of said subsequently arriving car; means operable, in the event that no car is present at said upper dispatch floor when said second named mechanism operates, to cause the starting signal then attempted to be given to be given to a car which thereafter arrives at said upper dispatch floor immediately upon the arrival of said subsequently arriving car; and means responsive to the arrival of any car at the lower dispatch floor, in the event that no car is present at said upper dispatch floor, to cause the giving of starting signals to all the other cars at the lower dispatch floor. 150

- lower and the upper dispatch floors; switching mechanism for the lower dispatch floor actuated by said timing mechanism upon the expiration of each scheduling interval for the lower dispatch floor; switching mechanism for the upper dispatch floor actuated by said timing mechanism upon the expiration of each scheduling interval for the upper dispatch floor; means responsive to said switching mechanism for the lower dispatch floor, when said switching mechanism is actuated by said timing mechanism, to cause the giving of the up start signal for such one car present at said lower dispatch floor with its up start signal operable, and, in the event no car is present at said lower dispatch floor with its up start signal operable at the time said switching mechanism for the lower dispatch floor is actuated, to cause the giving of the up start signal to the first car arriving at said lower dispatch floor and having its up start signal rendered operable; means responsive to said switching mechanism for the upper dispatch floor, when said switching mechanism is actuated by said timing mechanism, to cause the giving of the down start signal for such one car present at said upper dispatch floor with its down start signal operable, and in the event no car is present at said upper dispatch floor with its down start signal operable at the time said switching mechanism for the upper dispatch floor is actuated, to cause the giving of the down start signal to the first car arriving at said upper dispatch floor and having its down start signal rendered operable; and means operable at a definite instant after the actuation of both of said switching mechanisms to stop said timing mechanism and suspend the measurement of the scheduling intervals then in process of measurement; a plurality of devices, one for each car for each of the two dispatch floors, each device being operable upon the departure of its associated car from the dispatch floor for which it is provided in the direction of the other dispatch floor; and means responsive to the operation of one of said devices for the lower dispatch floor at any time after the actuation of said switching mechanism for the lower dispatch floor and before said definite instant, together with the operation of one of said devices for the upper dispatch floor at any time after the actuation of said switching mechanism for the upper dispatch floor and before said definite instant, as a result of the departure of a car from each dispatch floor during the time intervals specified for said floors, respectively, to render said time suspending means ineffective.
19. In a dispatching and scheduling system for a plurality of elevator cars; a lower dispatch floor and an upper dispatch floor; an up start signal for each car for dispatching the cars from the lower dispatch floor; a down start signal for each car for dispatching the cars from the upper dispatch floor; means responsive to the arrival of any car at the lower dispatch floor, in the event no other car is present at such lower floor, to render the up start signal for such arrived car operable to the exclusion of the up start signals for all the other cars; means responsive to the arrival of any car at the upper dispatch floor, in the event no other car is present at such upper floor, to render the down start signal for such arrived car operable to the exclusion of the down start signals for all the other cars; timing mechanism normally operating continuously to measure off regular scheduling intervals for both the lower and the upper dispatch floors; switching mechanism for the lower dispatch floor actuated by said timing mechanism upon the expiration of each scheduling interval for the lower dispatch floor; switching mechanism for the upper dispatch floor actuated by said timing mechanism upon the expiration of each scheduling interval for the upper dispatch floor; means responsive to said switching mechanism for the lower dispatch floor, when said switching mechanism is actuated by said timing mechanism, to cause the giving of the up start signal for such one car present at said lower dispatch floor with its up start signal operable, and, in the event no car is present at said lower dispatch floor with its up start signal operable at the time said switching mechanism for the lower dispatch floor is actuated, to cause the giving of the up start signal to the first car arriving at said lower dispatch floor and having its up start signal rendered operable; means responsive to said switching mechanism for the upper dispatch floor, when said switching mechanism is actuated by said timing mechanism, to cause the giving of the down start signal for such one car present at said upper dispatch floor with its down start signal operable, and in the event no car is present at said upper dispatch floor with its down start signal operable at the time said switching mechanism for the upper dispatch floor is actuated, to cause the giving of the down start signal to the first car arriving at said upper dispatch floor and having its down start signal rendered operable; and means operable at a definite instant after the actuation of both of said switching mechanisms to stop said timing mechanism and suspend the measurement of the scheduling intervals then in process of measurement; a plurality of devices, one for each car for each of the two dispatch floors, each device being operable upon the departure of its associated car from the dispatch floor for which it is provided in the direction of the other dispatch floor; and means responsive to the operation of one of said devices for the lower dispatch floor at any time after the actuation of said switching mechanism for the lower dispatch floor and before said definite instant, together with the operation of one of said devices for the upper dispatch floor at any time after the actuation of said switching mechanism for the upper dispatch floor and before said definite instant, as a result of the departure of a car from each dispatch floor during the time intervals specified for said floors, respectively, to render said time suspending means ineffective.
20. In a dispatching and scheduling system for a plurality of elevator cars; a dispatch floor; a plurality of starting signals, one for each of said cars, for dispatching said cars from said dispatch floor; operating mechanism for said starting signals; means for causing said mechanism to initiate the giving of a starting signal to any one of said cars at said dispatch floor; means operable, in the event that no car is at said dispatch floor capable of receiving a starting signal at the time said first named means operates, to relay the operation of said first named means to a car at said dispatch floor which subsequently becomes capable of receiving a starting signal, at the time such car becomes capable of receiving a starting signal, and also operable, after a starting signal is once given to a car, to maintain in operation such starting signal until a car departs from said dispatch floor; and means operable after each operation of said first named means, to render said first named means ineffective to initiate the giving of subsequent starting signals until a car has departed from said dispatch floor.
21. In a dispatching and scheduling system for a plurality of elevator cars; a dispatch floor; a

- plurality of starting signals, one for each of said cars, for dispatching said cars from said dispatch floor; operating mechanism for said starting signals; means for causing said mechanism to initiate the giving of a starting signal to any one of said cars at said dispatch floor; means operable, in the event that no car is at said dispatch floor capable of receiving a starting signal at the time said first named means operates, to relay the operation of said first named means to the first of said cars at said dispatch floor which becomes capable of receiving a starting signal at the time such car becomes capable of receiving a starting signal, and also operable, after a starting signal is once given to a car, to maintain in operation such starting signal for such car until such car responds to such starting signal; and means, operable after each operation of said first named means, to render said first named means ineffective to initiate the giving of subsequent starting signals until the starting signal initiated by said first named means has been given to a car and has been responded to by such car.
22. In a dispatching and scheduling system for a plurality of elevator cars; a dispatch floor; a plurality of starting signals, one for each of said cars for dispatching said cars from said dispatch floor; selecting mechanism adapted to render operable the starting signal for one of said cars positioned at said dispatch floor; operating mechanism for said starting signals, said operating mechanism including a switch mechanism which, when actuated to its operated position, remains in said operated position until reset to its initial position; contacts actuated by said switching mechanism, and brought into engagement when said switching mechanism is actuated to its operated position, for causing the operation of the operable starting signal, and in the event no starting signal has been rendered operable at the time said contacts are brought into engagement, for causing the operation of the starting signal which first is rendered operable, said contacts, also being operable, once a starting signal is caused to operate, for causing said starting signal to be maintained in operation; and means operated upon the departure of a car after said switching mechanism is actuated to its operated position for causing said switching mechanism to be reset to its initial position and thus terminate the maintained starting signal.
23. In a dispatching and scheduling system for a plurality of elevator cars; a lower and an upper dispatch floor; starting signals for said cars for dispatching said cars from said dispatch floors; mechanism for the lower dispatch floor operable to cause the giving of a starting signal to one of said cars that may be at said lower dispatch floor; mechanism for the upper dispatch floor operable to cause the giving of a starting signal to one of said cars that may be at said upper dispatch floor; means for causing one of said mechanisms normally to operate to cause the giving of starting signals to cars at the dispatch floor corresponding thereto at regular intervals of time; means for causing the other of said mechanisms to operate at a predetermined instant relative to the operation of the first of said mechanisms; and means, when operated, for causing a displacement in the times of operation of said mechanism relative to each other by an amount substantially equal to one-half of a regular time interval.
24. In a dispatching and scheduling system for a plurality of elevator cars; a lower and an upper dispatch floor; starting signals for said cars for dispatching said cars from said dispatch floors; mechanism for the lower dispatch floor operable to cause the giving of a starting signal to one of said cars that may be at said lower dispatch floor; mechanism for the upper dispatch floor operable to cause the giving of a starting signal to one of said cars that may be at said upper dispatch floor; timing means for causing one of said mechanisms normally to operate to cause the giving of starting signals to cars at the dispatch floor corresponding thereto at regular intervals of time; means for causing the other of said mechanisms to operate at a predetermined instant relative to the operation of the first of said mechanisms; and means, when operated, for causing a displacement in the times of operation of said mechanism relative to each other by an amount substantially equal to one-half of a regular time interval.
25. In a dispatching and scheduling system for a plurality of elevator cars; a lower and an upper dispatch floor; starting signals for said cars for dispatching said cars from said dispatch floors; mechanism for the lower dispatch floor operable to cause the giving of a starting signal to one of said cars that may be at said lower dispatch floor; mechanism for the upper dispatch floor operable to cause the giving of a starting signal to one of said cars that may be at said upper dispatch floor; means for causing one of said mechanisms normally to operate to cause the giving of starting signals to cars at the dispatch floor corresponding thereto at regular intervals of time; means for causing the other of said mechanisms to operate at a predetermined instant relative to the operation of the first of said mechanisms; and means, when operated, for causing a displacement in the times of operation of said mechanism relative to each other by an amount substantially equal to one-half of a regular time interval; and means operable, in the event that by a certain time after the operation of both of said mechanisms two cars have not left the dispatch floors, one car from the lower dispatch floor and the other car from the upper dispatch floor, to suspend further operations of both of said mechanisms until one car has left the lower dispatch floor and another car has left the upper dispatch floor.
26. In a dispatching and scheduling system for a plurality of elevator cars; a lower and an upper dispatch floor; starting signals for said cars for dispatching said cars from said dispatch floors; mechanism for the lower dispatch floor operable to cause the giving of a starting signal to one of said cars that may be at said lower dispatch floor; mechanism for the upper dispatch floor operable to cause the giving of a starting signal to one of said cars that may be at said upper dispatch floor; timing means for causing one of said mechanisms normally to operate to cause the giving of starting signals to cars at the dispatch floor corresponding thereto at regular intervals of time; means for causing the other of said mechanisms to operate at a predetermined instant relative to the operation of the first of said mechanisms; and means, when operated, for causing a displacement in the times of operation of said mechanism relative to each other by an amount substantially equal to one-half of a regular time interval; and means operable, in the event that by a certain time after the operation of both of said mechanisms two cars have not left the dispatch floors, one car from the lower dispatch floor and the other car from the upper dispatch floor, to suspend further operations of both of said mechanisms until one car has left the lower dispatch floor and another car has left the upper dispatch floor.

- tervals of time; means for causing the other of said mechanisms to operate at a predetermined instant relative to the operation of the first of said mechanisms; means, when operated, for 5 causing a displacement in the times of operation of said mechanisms relative to each other by an amount substantially equal to one-half of a regular time interval; means, operable at a certain instant after both of said mechanisms have operated, adapted to cause said timing means to suspend operation; a plurality of devices, one for each of said cars for each of said dispatch floors, each device being operable upon the departure of its associated car from the dispatch floor for 10 which it is provided; and means, responsive to the operation of one of said devices for the lower dispatch floor at any time after the operation of said mechanism for the lower dispatch floor and before said certain instant, together with 15 the operation of one of said devices for the upper dispatch floor at any time after the operation of said mechanism for the upper dispatch floor and before said certain instant, for causing said timing suspending means to be ineffective.
- 20 25 27. In a dispatching and scheduling system for a plurality of elevator cars; a lower and an upper dispatch floor; starting signals for said cars for dispatching said cars from said dispatch floors; means for rendering the starting light for any 30 number of said cars subject to the control of said dispatching and scheduling system; mechanism for the lower dispatch floor operable to cause the giving of a starting signal to one of said cars included in said system that may be at said lower dispatch floor; mechanism for the upper dispatch floor operable to cause the giving of a starting signal to one of said cars included in said system that may be at said upper dispatch floor; means for causing one of said mechanisms normally to 35 operate to cause the giving of starting signals to cars at the dispatch floor corresponding thereto at regular intervals of time; means for causing the other of said mechanisms to operate at either one of two predetermined instants relative to the 40 operation of the first of said mechanisms, said predetermined instants having a time interval between them substantially equal to one-half of a regular time interval; and switching mechanism with two operable positions, one position 45 for when an even number of said cars are included in said system and the other position for when an odd number of said cars are included in said system, for causing, when in one of said operable positions, the other of said mechanisms to 50 operate at one of said predetermined instants, and for causing, when in the other of said operable positions, the other of said mechanisms to operate at the other of said predetermined instants.
- 55 60 28. In a dispatching system for a plurality of elevator cars; a dispatch floor; a plurality of starting signals, one for each of said cars, for dispatching said cars from said dispatch floor; and switching mechanism responsive to the arrival of each car at said dispatch floor at all times when no other cars are at said dispatch floor for causing the giving of the starting signal for such arrived car immediately upon its arrival at said dispatch floor.
- 65 70 29. In a dispatching system for a plurality of elevator cars; a dispatch floor; a plurality of starting signals, one for each of said cars, for dispatching said cars from said dispatch floor; and switching mechanism for causing the giving 75 of said starting signals for said cars at all times immediately upon their arrival at said dispatch floor provided that when each car arrives there is no other car at said dispatch floor, and for causing whenever there is more than one car at said dispatch floor, the giving of the starting signals for the cars at said dispatch floor successively, one at a time, upon, and as a result of, the departure of each car that has received the last-given starting signal. 80
30. In a dispatching and scheduling system for a plurality of elevator cars; a dispatch floor; a plurality of starting signals one for each of said cars, for dispatching said cars from said dispatch floor; mechanism adapted upon each operation to cause the giving of a starting signal to one of said cars at said dispatch floor; means for causing said mechanism normally to operate at regular intervals of time; and means, adapted to be rendered effective during a heavy traffic period, for causing said mechanism to operate to cause the giving of a starting signal to a car at all times immediately upon the arrival of such car at said dispatch floor in the event no other car is at said dispatch floor at the time of arrival of such car thereat. 85
31. In a dispatching and scheduling system for a plurality of elevator cars; a dispatch floor; a starting signal for dispatching each of said cars from said dispatch floor; operating mechanism for said starting signals; means for causing said mechanism to operate a starting signal for only one of said cars that may be at said dispatch floor, to the exclusion of all other cars, upon each successive operation of said mechanism; means for causing said mechanism normally to operate to give said starting signals for said cars at regular intervals of time; means responsive to the non-departure of a car from said dispatch floor during the interval from the time said mechanism operates to cause the giving of a starting signal, to a predetermined time thereafter, to delay the operation of said mechanism at least until a car departs from said dispatch floor; and means, adapted to be rendered effective during a heavy traffic period, for causing said mechanism to operate to cause the giving of a starting signal to a car at all times immediately upon the arrival of such car at said dispatch floor in the event no other car is at said dispatch floor at the time of arrival of such car thereat, and for causing said delaying means to be ineffective. 90
32. In a dispatching and scheduling system for a plurality of elevator cars; a lower and an upper dispatch floor; starting signals for said cars for dispatching said cars from said dispatch floors; mechanism adapted upon each operation to cause the giving of a starting signal to but one of said cars at one of said dispatch floors; means for causing said mechanism normally to operate to cause the giving of starting signals to said cars at said one of said dispatch floors at regular intervals of time; and additional mechanism adapted to cause the giving of a starting signal to each of said cars at the other dispatch floor at all times immediately upon the arrival of such car at said other dispatch floor in the event no other car is at said other dispatch floor at the time of the arrival of such car thereat. 95
33. In a dispatching and scheduling system for a plurality of elevator cars; a lower and an upper dispatch floor; starting signals for said cars for dispatching said cars from said dispatch floors; mechanism adapted upon each operation to cause the giving of a starting signal to one of said 100
- 105 110 115 120 125 130 135 140 145 150

- cars at said lower dispatch floor and to another one of said cars at said upper dispatch floor; timing means for causing said mechanism normally to operate at regular intervals of time and thus normally dispatch said cars from each said dispatch floors at regular intervals of time; and means, responsive to the arrival of each car at one of said dispatch floors in the event no other car is at said one dispatch floor at the time of arrival thereof of such car, and adapted to be rendered effective during a heavy traffic period, for causing the giving of a starting signal to such arrived car at said one dispatch floor at all times immediately upon its arrival thereat, regardless of said regular intervals of time. 80
34. In a dispatching and scheduling system for a plurality of elevator cars; a lower and an upper dispatch floor; a plurality of up starting signals, one for each of said cars, for dispatching said cars from said lower dispatch floor; a plurality of down starting signals, one for each of said cars, for dispatching said cars from said upper dispatch floor; operating mechanism for said up starting signals; operating mechanism for said down starting signals; means for causing said operating mechanism for said down starting signals to operate at a definite instant relative to the operation of said operating mechanism for the up starting signals; means for causing each successive operation of said operating mechanism for the up starting signals to operate an up starting signal for only one of said cars at the lower dispatch floor, to the exclusion of all other cars; means for causing each successive operation of said operating mechanism for the down starting signals to operate a down starting signal for only one of said cars at the upper dispatch floor, to the exclusion of all other cars; timing means for causing said operating mechanism normally to operate to give said starting signals at regular intervals of time; and means, adapted to be rendered effective during heavy traffic periods, for rendering either or both of said operating mechanisms unresponsive to said timing means and for causing at all times the immediate giving of such starting signals which are normally operated by such operating mechanisms that have been rendered unresponsive, to the cars as they arrive at the dispatch floors corresponding to such unresponsive operating mechanisms, without regard to the regular intervals of time, provided no other car is at such dispatch floor at which such car arrives at the time of its arrival thereat. 90
35. In a dispatching and scheduling system for a plurality of elevator cars; a lower and an upper dispatch floor; starting signals for said cars for dispatching said cars from said dispatch floors; switching mechanism for each car for each dispatch floor, each of said switching mechanisms, when operated, rendering operable a starting signal for dispatching its corresponding car from the dispatch floor for which said switching mechanism is provided, and also rendering inoperative all other of said switching mechanisms provided for the same dispatch floor thereby preventing the giving of starting signals to other cars at the same dispatch floor; means responsive to the presence of each car at each dispatch floor when no switching mechanism is operated for any other car for the dispatch floor at which such car is present, for causing the operation of the switching mechanism for such car for such dispatch floor continuously as long as such car remains at such dispatch floor; operating mechanism adapt- 95
- ed upon each operation to cause the giving of an operable starting signal for dispatching the associated car from the lower dispatch floor and the giving of an operable starting signal for dispatching the associated car from the upper dispatch floor; timing means for causing said operating mechanism normally to operate at regular intervals of time; and means, adapted to be rendered effective during a heavy traffic period, for rendering said timing means ineffective to cause the operation of said operating mechanism at regular intervals of time, and for causing the giving of said starting signals to said cars at all times immediately upon their arrival at said dispatch floors provided that when each car arrives at a dispatch floor there is no other car at such dispatch floor. 100
36. In a dispatching and scheduling system for a plurality of elevator cars; a lower and an upper dispatch floor; starting signals for said cars for dispatching said cars from said dispatch floors; switching mechanism for each car for each dispatch floor, each of said switching mechanisms, when operated, causing the operation of a starting signal for dispatching its corresponding car from the dispatch floor for which said switching mechanism is provided, and also causing all other of said switching mechanisms provided for the same dispatch floor to be inoperative to cause the giving of starting signals to other cars at the same dispatch floor; and means responsive to the presence of each car at each dispatch floor when no switching mechanism is operated for any other car for the dispatch floor at which such car is present, for causing the operation of the switching mechanism for such car for such dispatch floor continuously as long as such car remains at such dispatch floor. 105
37. In a dispatching and scheduling system for a plurality of elevator cars; a dispatch floor; a plurality of starting signals, one for each of said cars, for dispatching said cars from said dispatch floor; operating mechanism for said starting signals; means for causing said mechanism to operate a starting signal for only one of said cars that may be at said dispatch floor, to the exclusion of all other cars, upon each successive operation of said mechanism; means for causing said mechanism normally to operate to give said starting signals for said cars at regular intervals of time; and means for preventing the car operators for all cars at said dispatch floor other than for the car which has received a starting signal from causing the departure of their respective cars from said dispatch floor until said car that has received a starting signal has left said dispatch floor. 110
38. In a dispatching and scheduling system for a plurality of elevator cars; a dispatch floor; switching mechanism for each of said cars operable to cause the starting of the corresponding car from said dispatch floor; a plurality of starting signals, one for each of said cars, for dispatching said cars from said dispatch floor; operating mechanism for said starting signals; means for causing said operating mechanism to operate a starting signal for only one of said cars that may be at said dispatch floor to the exclusion of all other cars, upon each successive operation of said operating mechanism; means for causing said operating mechanism normally to operate to give said starting signals for said cars at regular intervals of time; means for rendering said switching mechanism for each of said cars at said dispatch floor ineffective to cause the starting of the 115

- cars from said dispatch floor from the times of arrival of such cars thereat; and means actuated at the time a starting signal is given to a car at said dispatch floor for rendering said last mentioned means for that car ineffective so that that car may be started from said dispatch floor. 80
39. In a dispatching and scheduling system for a plurality of elevator cars; a lower and an upper dispatch floor; switching mechanism for each of 10 said cars operable to cause the starting of the corresponding car from the lower and the upper dispatch floor; starting signals for said cars for dispatching said cars from said dispatch floors; operating mechanism for said starting signals 15 operable for the lower and the upper dispatch floors; means for causing said operating mechanism to operate a starting signal for only one of said cars at said lower dispatch floor to the exclusion of all other cars upon each successive 20 operation thereof for the lower dispatch floor; means for causing said operating mechanism to operate a starting signal for only one of said cars at said upper dispatch floor to the exclusion of all other cars upon each successive operation 25 thereof for the upper dispatch floor; means for causing said operating mechanism normally to operate to give said starting signals for the lower and the upper dispatch floors at regular intervals of time; non-start means for rendering said 30 switching mechanism for each of said cars at said dispatch floors ineffective to cause the starting of the cars from the respective dispatch floors from the times of arrival of such cars at said dispatch floors; means actuated at the time a starting 35 signal is given to a car at the lower dispatch floor for rendering said non-start means for that car ineffective so that that car may be started from said lower dispatch floor; and means actuated at the time a starting signal is given to a car 40 at the upper dispatch floor for rendering said non-start means for that car ineffective so that that car may be started from the upper dispatch floor. 45
40. In a dispatching and scheduling system for a plurality of elevator cars; a dispatch floor; controlling mechanism for each of said cars for causing the starting of the corresponding car from said dispatch floor; non-start means responsive to the arrival of each car at said 50 dispatch floor adapted to render said controlling mechanism for the corresponding car ineffective for starting said car from said dispatch floor; a plurality of starting signals, one for each of said cars, for dispatching said cars from said dispatch floor; a plurality of switching mechanisms, one for each of said cars, each of said switching mechanisms, when operated when the corresponding car 55 is at said dispatch floor, rendering operable the starting signal for the corresponding car and causing all other of said switching mechanisms to be ineffective to render their corresponding starting signals operable; means responsive to the presence of each car at said dispatch floor when no switching mechanism is operated for any other 60 car for causing the operation of the switching mechanism for such car at said dispatch floor; and means for causing the operation of the operable starting signal for such car for which the switching mechanism is operated, and at the same time 65 for causing said non-start means for only such car to be rendered ineffective so that only such car may be started from said dispatch floor. 70
41. In a dispatching and scheduling system for a plurality of elevator cars; a dispatch floor; starting mechanism for each of said cars for 75 causing the starting of the corresponding car from said dispatch floor; non-start means responsive to the arrival of each car at said dispatch floor adapted to render said starting mechanism for the corresponding car ineffective for starting such car from said dispatch floor; switching mechanism adapted upon each operation to render ineffective the non-start means for only one of said cars at said dispatch floor, and thus to render effective said starting mechanism for such one car; and means for causing said switching mechanism normally to operate at regular intervals of time. 85
42. In a dispatching system for a plurality of elevator cars; a dispatch floor; starting mechanism for each of said cars for causing the starting of the corresponding car from said dispatch floor; and switching mechanism responsive to the presence of two or more cars at said dispatch floor for rendering the starting mechanisms for all but one of said cars at said dispatch floor ineffective to start their corresponding cars until after such one car has left said dispatch floor. 90
43. In a dispatching and scheduling system for a plurality of elevator cars; a dispatch floor; a plurality of signals, one for each of said cars, for indicating the car which is to be the next to leave said dispatch floor; starting mechanism for each of said cars for causing the starting of the corresponding car from said dispatch floor; switching mechanism responsive to the presence of two or more cars at said dispatch floor for rendering the starting mechanisms for all but one of said cars at said dispatch floor ineffective to start their corresponding cars until after such one car has left said dispatch floor; and operating mechanism for said signals for causing the operation of only the signal for such one car prior to its departure from said dispatch floor. 100
44. In a dispatching and scheduling system for a plurality of elevator cars; a dispatching floor; a plurality of signals, one for each of said cars, for indicating the car which is to be the next to leave said dispatch floor; a plurality of starting signals, one for each of said cars, for dispatching said cars from said dispatch floor; starting mechanism for each of said cars for causing the starting of the corresponding car from said dispatch floor; non-start means responsive to the arrival of each car at said dispatch floor adapted to render said starting mechanism for the corresponding car ineffective for starting such car from said dispatch floor; a plurality of switching mechanisms, one for each of said cars, each of said switching mechanisms, when operated when the corresponding car is at said dispatch floor, causing the operation of the indicating signal for the corresponding car, rendering operable the starting signal for the corresponding car, and causing all other of said switching mechanisms to be ineffective; means responsive to the presence of each car at said dispatch floor when no switching mechanism is operated for any other car for causing the operation of the switching mechanism for such car at said dispatch floor; and means for causing the operation of the operable starting signal for such car for which the switching mechanism is operated, and at the same time for causing said non-start means for only such car to be rendered ineffective so that only such car may be started from said dispatch floor, thereby preventing the starting of all cars from said dispatch floor except that car which has had its indicating and starting signals operated. 110
45. In a dispatching and scheduling system 115

for a plurality of elevator cars; a dispatch floor; a plurality of starting signals, one for each of said cars, for dispatching said cars from said dispatch floor; operating mechanism adapted upon each operation to cause the giving of a starting signal to one of said cars at said dispatch floor, to the exclusion of all other cars, and operable in the event no car is present at said dispatch floor when said operating mechanism operates, to cause the starting signal thus attempted to be given to be given to a car which thereafter arrives at said dispatch floor; signalling mechanism for informing the starter of operating conditions at said dispatch floor; means adapted to be actuated upon the operation of said mechanism for causing said signalling mechanism to be operative in one manner; and means actuated upon the actual operation of a starting signal for a car at said dispatch floor for causing said signalling mechanism to be operated in another manner.

46. In a dispatching and scheduling system for a plurality of elevator cars; a dispatch floor; a plurality of starting lights, one for each of said cars, for dispatching said cars from said dispatch floor; operating mechanism adapted upon each operation to cause the operation of a starting light for one of said cars at said dispatch floor, to the exclusion of all other cars, and operable in the event no car is present at said dispatch floor when said operating mechanism operates, to cause the then-attempted operation of a starting light to be effective to cause the operation of the starting light for a car which thereafter arrives at said dispatch floor; a starter's light for indicating operating conditions to the starter; means responsive to the operation of said operating mechanism, for causing, in the event no car is at said dispatch floor, a steady illumination of said starter's light, and for causing, in the event a car is at said dispatch floor with its starting signal being operated, a flickering illumination of said starter's light; and means responsive to the departure of a car from said dispatch floor after and operation of said operating mechanism adapted to extinguish both the starter's light and the operated starting light.
